UNITED STATES PATENT OFFICE.

TALBOT G. MARTIN, OF CHICAGO, ILLINOIS, ASSIGNOR, BY MESNE ASSIGNMENTS, TO
AUTOMATIC ELECTRIC COMPANY, A CORPORATION OF ILLINOIS.

TRUNKING ARRANGEMENT FOR AUTOMATIC TELEPHONE-EXCHANGES.

1,314,685.

Specification of Letters Patent.

Patented Sept. 2, 1919.

Application filed May 29, 1905, Serial No. 262,728. Renewed September 6, 1918. Serial No. 252,972.

To all whom it may concern:

Be it known that I, TALBOT G. MARTIN, a citizen of the United States of America, and resident of Chicago, Cook county, Illinois, 5 have invented a certain new and useful Improvement in Trunking Arrangements for Automatic Telephone-Exchanges, of which the following is a specification.

My invention relates to automatic telephone systems in general, but more particularly to telephone systems of that type in which the apparatus for establishing connection between one subscriber's line and another comprises a suitable number of step- 10 by-step switching machines, and especially to automatic step-by-step telephone switching apparatus in which the current, both for talking and signaling purposes, and also for operating the various switching machines at 15 the exchange or central station, is all furnished from suitable batteries and generators, or other sources of supply, located at the said exchange or central station.

Generally stated, the object of my invention is the provision of an improved construction and arrangement by which the subscribers of two automatic telephone exchanges, of the above general character, may be able to satisfactorily converse with each 20 other over trunk-line-circuits established from a calling subscriber's line entering one exchange to a called subscriber's line entering the other exchange, notwithstanding that ordinarily this could not be done satisfactorily, particularly where the length and 25 resistance of the trunk-lines are comparatively great.

Certain special objects are to provide an improved construction and arrangement involving a so-called repeater by which a subscriber of one exchange may connect his line with a subscriber of another exchange; to provide an improved construction and arrangement whereby talking current from the 30 battery or other central source of supply may be furnished to the called subscriber's line from the "connector," and through the repeater to the calling subscriber's line; to provide improved means for preventing the 35 energizing current for the talking circuits from being furnished thereto until the called subscriber has answered; to provide an improved construction and arrangement involving the use of a differential-relay in the 40 said repeater, and of such character that the

calling subscriber may be able to release—that is, to restore all of the different switching machines, such as "selectors" and a "connector," which may have been put in use between the two subscribers' lines, and in 60 case the called subscriber fails to hang up his receiver; to provide an improved arrangement of such character that when talking current is put on the lines, the circuit in the said repeater, and which controls the operating parts in certain portions of the system, will be opened and made non-effective through the use of a so-called bridge-cut-off and pole-changing-relay; to provide an improved construction and arrangement where- 65 by a single repeater may be provided with each trunk-line, as will hereinafter more fully appear; and to provide certain details and features of improvement, and certain novel features of construction and circuit 70 arrangement, tending to increase the general efficiency and serviceability of an automatic telephone system of this particular character, and tending to insure satisfactory telephone service between the subscribers of dif- 75 ferent automatic telephone exchanges. 80

I have already referred to switching machines called "selectors", and to other switching machines commonly known as "connectors". From the following description, it will be seen that a "selector" is an automatic step-by-step switching machine employed for enabling the calling subscriber to obtain connection with an idle trunk-line leading to the desired group of switches, 85 such as other "selectors" or "connectors", according to the size of the exchange. A "selector", whether it be a first, second or third, etc., is preferably so constructed that it is under the direct control of the calling 90 subscriber for the purpose of selecting a certain group of trunk-lines and switches, but is also constructed in such manner that it ceases to be under the direct control of the calling subscriber as soon as such selection 95 has been accomplished, the "selector" then proceeding automatically, and without the direction or control of the calling subscriber, to select the first idle trunk-line 100 which it encounters, inasmuch as any non-busy trunk-line in the selected group will answer the purpose of the calling subscriber. A "connector", however, is employed for making the final connection directly with the line of the called subscriber, and is di- 105 110

rected in its operations by and under the control of the calling subscriber throughout its entire operation—that is to say, it is under the direct control of the calling subscriber during the first part of its operation in which it picks out the particular group of subscribers' lines including the called subscriber's line, and is then controlled directly by the calling subscriber for the purpose of picking out the desired subscriber's line. In other words, both "selectors" and "connectors" can be operated or controlled by a calling subscriber for the purpose of picking out any particular group of lines; but the two types of switches differ in this respect, namely, that the selection of a particular line by a "selector" is strictly automatic, and a thing over which the calling subscriber has no control after he has caused the "selector" to pick out a certain group of lines; while on the other hand a "connector" can be operated by the calling subscriber for the purpose of picking out a certain group of lines, and its further operation for the purpose of picking out the particular line with which connection is desired is under the direct control of the calling subscriber, so that in operating a "connector", the selection of both the group and the particular or desired line in that group are determined by the calling subscriber. This is obviously practicable, and the natural method of operation, inasmuch as it matters not to the calling subscriber what particular trunk-lines are brought into use in connecting his line with the called subscriber's line; but when it comes to the final operation of selecting another subscriber's line, the calling subscriber then wants the connection extended to a particular subscriber's line, and to no other. Consequently, a "selector" is always free to search through the selected group of trunk-lines until it finds one which is idle or not in use, while the "connector" must proceed directly to the point where it can establish connection with the called subscriber's line, and must then either establish such connection, or, in the event that the called subscriber's line is found to be busy, then refuse to make the connection and restore itself automatically to its normal condition. In this way, a "connector" cannot be made to cut-in, so to speak, on a talking circuit which has already been established between two subscribers' stations.

To the foregoing and other useful ends my invention consists in matters hereinafter set forth and claimed.

60 In the accompanying drawings, Figure 1 is a diagrammatic representation of the sub-station A on the upper left-hand corner, in connection with its central station, which will be referred to as central No. 1.

65 Fig. 2 is a like representation of another

sub-station B on the upper right-hand corner, in connection with its central station, which will be referred to as central No. 2.

Fig. 1, in conjunction with Fig. 2, represents the circuits and switching apparatus 70 or mechanisms involved when a subscriber at sub-station A of central No. 1 has called a subscriber at sub-station B of central No. 2.

In Fig. 1, together with sub-station A 75 (which will be designated as station #6555), to the left of line X—X is represented that part of the switching apparatus or mechanism known as a "first-selector-switch" which belongs to sub-station #6555; to the 80 right of line X—X is that part D which constitutes my invention and is known as a "repeater".

In Fig. 2, together with sub-station B (which will be designated as sub-station 85 #2220), to the left of line Y—Y is represented that part of the switching apparatus E known as a "second-selector-switch", while between lines Y—Y and Z—Z is that part F known as a "connector-switch". To 90 the right of line Z—Z is the "first-selector" G that belongs to sub-station #2220.

Figs. 3, 4 and 5 respectively are diagrammatic perspective representations of the following switches: "first-selector" C, "second-selector" E and "connector" F.

Fig. 6 is a simplified diagram illustrating the method of supplying talking current to the talking-circuit formed by connecting together any two subscribers' lines. 100

Fig. 7 is a simplified diagram illustrating an arrangement which may be employed for trunking between two exchanges.

In Figs. 3, 4 and 5 there are also shown "private-banks" c, e and f with "private-trunk-lines" c¹, e¹ and f¹, and "line-bank-terminals" c², e² and f², with "line-trunks" c³ and c⁴; e³ and e⁴; and f³ and f⁴. Like all other sub-stations in this system, sub-station A is connected with its central station by 105 two metallic conductors 2 and 3 known as "vertical" and "rotary" lines, and is provided with the usual ringer a¹, receiver a², transmitter a³, induction-coil a⁴, condenser a⁵, and switch-hook a⁶, together with a signaling-button a⁷ and a calling device represented as having two push-buttons a⁸ and a⁹, in connection with a number of springs and other essential details of construction. The calling device, however, may be of any suitable design. In making a call, the metallic lines are alternately grounded a proper number of times, while the release, i. e., the restoring of all switching apparatus after a call, occurs when both lines are grounded simultaneously for a moment. The "first-selector" may be of any suitable, known or approved construction, C in Fig. 3 being a representative and well-known type. Proceeding to describe the mechanical parts, 110

represents a so-called "vertical-line-relay" with an armature c^8 , and c^7 represents a so-called "rotary-line-relay" having an armature c^8 . The so-called "vertical-magnet" c^9 5 has two coils c^{10} , c^{11} , and an armature c^{12} , which latter has two pivots c^{13} and c^{14} and is always under the tension of a retracting-spring c^{15} . The armature has an arm c^{16} provided with an L-shaped piece c^{17} , and 10 with a so-called "vertical-pawl" c^{18} , subject to the tension of a retracting-spring c^{19} . The so-called "release-magnet" c^{20} has an armature c^{21} provided with two pivots c^{22} and c^{23} , and is always under the tension of 15 the retracting-spring c^{24} . This armature has attached to it a so-called "release-link" c^{25} , on the other end of which there is a slot c^{26} . The said link, when the switch is in normal position, is engaged with the so-called "double-dog" c^{27} by means of the lug c^{28} . This "double-dog" has two pivots c^{29} and c^{30} , and is under the tension of the retracting-spring c^{31} ; it has two bent arms c^{32} , c^{33} and a downwardly-projecting arm c^{34} , which latter 20 engages with the link c^{35} . The so-called "rotary-magnet" c^{36} has two coils c^{37} , c^{38} , and an armature c^{39} , which latter has two pivots c^{40} and c^{41} , and which is always under the tension of the retracting-spring c^{42} . 25 This armature also has a so-called interrupter-arm c^{43} and a "rotary-armature-finger" c^{44} , and another arm c^{45} that carries a so-called "rotary-pawl" c^{46} at its extremity, which pawl is under the tension of the retracting-spring c^{47} . The so-called "private-magnet" c^{48} has an armature c^{49} provided with two pivots c^{50} , c^{51} , and a retracting-spring c^{52} . This armature also has an arm c^{53} which is provided with a lateral arm c^{54} 30 and with a saw-tooth escapement near its end having teeth c^{55} , c^{56} , c^{57} and c^{58} . The shaft c^{59} has, near its middle, a set of circular teeth c^{60} by means of which the "vertical-magnet" c^9 gives it a longitudinal step-by-step motion through the mechanisms on its 35 armature already referred to. There is a groove c^{61} along these circular teeth which receives an arm c^{62} with which the circular teeth engage, so that the shaft may be supported during rotary motion. Just below the circular teeth there is a set of longitudinal teeth c^{63} by means of which the "rotary-magnet" c^{36} imparts to the shaft c^{59} a rotary step-by-step motion, through means on its 40 armature, previously referred to. At the upper end of this shaft there is a coiled spring c^{64} , the outer end of which is fastened to the normal post c^{65} , and against the tension of which the shaft is rotated by the "rotary-magnet" c^{36} , and in this way the shaft 45 returns to its normal position, when it is made free, in a manner to be hereinafter explained. Just below this spring there is a stop-arm c^{66} that prevents the shaft from falling back more than it should while it is 50 returning to its normal position under the tension of the spring c^{64} . This arm also controls the position of the spring c^{67} with regard to contact-points c^{68} and c^{69} . Near the lower extremity of the shaft there is a switching-arm c^{70} , or so-called "private-wiper". Still farther below this are the "vertical-line-wiper" c^{71} and the "rotary-line-wiper" c^{72} , separated by suitable insulation c^{73} . Near the middle of the shaft is a cam c^{74} which prevents the arm c^{75} from moving too much, at certain times, under the tension of the spring c^{76} , through the interference of the lug c^{77} . Near the middle of this arm c^{75} there are two pivots c^{78} and c^{79} , 55 while near the left extremity of the same there is a lateral arm c^{80} and a vertical shaft c^{81} . On this shaft there are four arms or wipers c^{82} , c^{83} , c^{84} and c^{85} . The arm c^{75} , with all the appended parts, is known as a "side-switch". When this arm c^{75} is behind tooth c^{55} , the "side-switch" is in what is known as its first position, "side-switch-wipers" c^{82} , c^{83} , c^{84} and c^{85} being in contact with points c^{86} , c^{87} , c^{88} and c^{89} , respectively. When the "side-switch-arm" c^{75} is between teeth c^{55} and c^{57} , the "side-switch" is then in what is known as second position, the same "side-switch-wipers" shifting into contact with points c^{90} , c^{91} , c^{92} and c^{93} , respectively; and 60 when it disengages with tooth c^{58} , and falls against stop c^{98} , the "side-switch" is then in the third position, the "side-switch-wipers" being then in contact with points c^{94} , c^{95} , c^{96} and c^{97} , respectively. The so-called "bridge-cut-off-relay" c^{99} has an armature c^{100} . The so-called "back-release-relay" c^{101} has an armature c^{102} ; H^1 representing the battery used for calling and talking purposes, and h representing its grounded terminal. 65

The repeater of my invention has no movable parts, such as the shafts and release mechanism used in "selectors" and "connectors", but is made up of a number of relays and springs and other details herein-after pointed out. This instrument is designed to be bridged permanently across the trunk-lines leading to a distant exchange. In this repeater D (Fig. 1), d represents a "vertical-line-relay" having an armature d^1 70 by means of which impulses sent over the "vertical-line-conductor" 2 are repeated to the so-called "vertical-trunk-line-conductor" 4 that leads to any suitable instrument at the distant station, and in this case to a "second-selector" E at central station #2 (Fig. 2). The "rotary-line-relay" d^3 has an armature d^4 , by means of which impulses coming from subscriber-A's station over the "rotary-line-conductor" 3 are repeated in the "rotary-line-conductor" 5 that leads to the same instrument at central station #2. The differential-relay d^5 , having two windings d^6 and d^7 , and the armature d^8 , is of such a 75 nature that current passing through only one 80

1,814,685

8

represents a so-called "vertical-line-relay" with an armature c^8 , and c^7 represents a so-called "rotary-line-relay" having an armature c^8 . The so-called "vertical-magnet" c^9 5 has two coils c^{10} , c^{11} , and an armature c^{12} , which latter has two pivots c^{13} and c^{14} and is always under the tension of a retracting-spring c^{15} . The armature has an arm c^{16} provided with an L-shaped piece c^{17} , and 10 with a so-called "vertical-pawl" c^{18} , subject to the tension of a retracting-spring c^{19} . The so-called "release-magnet" c^{20} has an armature c^{21} provided with two pivots c^{22} and c^{23} , and is always under the tension of 15 the retracting-spring c^{24} . This armature has attached to it a so-called "release-link" c^{25} , on the other end of which there is a slot c^{26} . The said link, when the switch is in normal position, is engaged with the so-called "double-dog" c^{27} by means of the lug c^{28} . This "double-dog" has two pivots c^{29} and c^{30} , and is under the tension of the retracting-spring c^{31} ; it has two bent arms c^{32} , c^{33} and a downwardly-projecting arm c^{34} , which latter 20 engages with the link c^{35} . The so-called "rotary-magnet" c^{36} has two coils c^{37} , c^{38} , and an armature c^{39} , which latter has two pivots c^{40} and c^{41} , and which is always under the tension of the retracting-spring c^{42} . 25 This armature also has a so-called interrupter-arm c^{43} and a "rotary-armature-finger" c^{44} , and another arm c^{45} that carries a so-called "rotary-pawl" c^{46} at its extremity, which pawl is under the tension of the retracting-spring c^{47} . The so-called "private-magnet" c^{48} has an armature c^{49} provided with two pivots c^{50} , c^{51} , and a retracting-spring c^{52} . This armature also has an arm c^{53} which is provided with a lateral arm c^{54} 30 and with a saw-tooth escapement near its end having teeth c^{55} , c^{56} , c^{57} and c^{58} . The shaft c^{59} has, near its middle, a set of circular teeth c^{60} by means of which the "vertical-magnet" c^9 gives it a longitudinal step-by-step motion through the mechanisms on its armature already referred to. There is a groove c^{61} along these circular teeth which receives an arm c^{62} with which the circular teeth engage, so that the shaft may be supported during rotary motion. Just below the circular teeth there is a set of longitudinal teeth c^{63} by means of which the "rotary-magnet" c^{36} imparts to the shaft c^{59} a rotary step-by-step motion, through means on its 35 armature, previously referred to. At the upper end of this shaft there is a coiled spring c^{64} , the outer end of which is fastened to the normal post c^{65} , and against the tension of which the shaft is rotated by the "rotary-magnet" c^{36} , and in this way the shaft 40 returns to its normal position, when it is made free, in a manner to be hereinafter explained. Just below this spring there is a stop-arm c^{66} that prevents the shaft from falling back more than it should while it is 45 returning to its normal position under the tension of the spring c^{64} . This arm also controls the position of the spring c^{67} with regard to contact-points c^{68} and c^{69} . Near the lower extremity of the shaft there is a switching-arm c^{70} , or so-called "private-wiper". Still farther below this are the "vertical-line-wiper" c^{71} and the "rotary-line-wiper" c^{72} , separated by suitable insulation c^{73} . Near the middle of the shaft is a cam c^{74} which prevents the arm c^{75} from moving too much, at certain times, under the tension of the spring c^{76} , through the interference of the lug c^{77} . Near the middle of this arm c^{75} there are two pivots c^{78} and c^{79} , 50 while near the left extremity of the same there is a lateral arm c^{80} and a vertical shaft c^{81} . On this shaft there are four arms or wipers c^{82} , c^{83} , c^{84} and c^{85} . The arm c^{75} , with all the appended parts, is known as a "side-switch". When this arm c^{75} is behind tooth c^{55} , the "side-switch" is in what is known as its first position, "side-switch-wipers" c^{82} , c^{83} , c^{84} and c^{85} being in contact with points c^{86} , c^{87} , c^{88} and c^{89} , respectively. When the "side-switch-arm" c^{75} is between teeth c^{55} and c^{57} , the "side-switch" is then in what is known as second position, the same "side-switch-wipers" shifting into contact with points c^{90} , c^{91} , c^{92} and c^{93} , respectively; and 55 when it disengages with tooth c^{58} , and falls against stop c^{98} , the "side-switch" is then in the third position, the "side-switch-wipers" being then in contact with points c^{94} , c^{95} , c^{96} and c^{97} , respectively. The so-called "bridge-cut-off-relay" c^{99} has an armature c^{100} . The so-called "back-release-relay" c^{101} has an armature c^{102} ; H^1 representing the battery used for calling and talking purposes, and h representing its grounded terminal. 60

The repeater of my invention has no movable parts, such as the shafts and release mechanism used in "selectors" and "connectors", but is made up of a number of relays and springs and other details herein-after pointed out. This instrument is designed to be bridged permanently across the trunk-lines leading to a distant exchange. In this repeater D (Fig. 1), d represents a "vertical-line-relay" having an armature d^1 65 by means of which impulses sent over the "vertical-line-conductor" 2 are repeated to the so-called "vertical-trunk-line-conductor" 4 that leads to any suitable instrument at the distant station, and in this case to a "second-selector" E at central station #2 (Fig. 2). The "rotary-line-relay" d^3 has an armature d^4 , by means of which impulses coming from subscriber-A's station over the "rotary-line-conductor" 3 are repeated in the "rotary-line-conductor" 5 that leads to the same instrument at central station #2. The differential-relay d^5 , having two windings d^6 and d^7 , and the armature d^8 , is of such a 70 nature that current passing through only one 75

of its coils will actuate its armature; also, if the two left-hand terminals were connected together, and the two right-hand terminals were connected together, and current passes from one of the combined terminals to the other, the armature will also be actuated; but if the two left-hand terminals are left together, while the right-hand terminals are separated—current being sent from 10 one of these separated terminals to the other—the armature will not be actuated. The office of this relay is to provide means whereby the calling subscriber may be able to release, even if the subscriber whom he 15 has called does not restore his receiver to the hook. Furthermore, the differential-coil prevents impulses that have been repeated from the subscriber's "vertical-line-conductor" 2 to the "vertical-trunk-line-conductor" 4 from passing to the "rotary-trunk-line-conductor" 5, and likewise prevents impulses coming from the subscriber's "rotary-line-conductor" 3, and repeated to the "rotary-trunk-line-conductor" 5, from passing 20 over to the "vertical-trunk-line-conductor" 4, in a manner that shall be hereinafter explained. The bridge-cut-off-relay d^9 —the office of which shall be explained later—has an armature d^{10} . As illustrated, d^{11} represents a dead resistance of substantially 60 ohms, while d^{12} and d^{13} represent two condensers.

The "second-selector" is very nearly the same as the "first-selector"; for in Fig. 4, 35 e^5 and e^7 represent the "vertical" and "rotary" "line-relays", e^6 and e^8 representing their respective armatures. The "vertical-magnet" e^9 has two coils e^{10} and e^{11} ; and the usual armature e^{12} is provided with pivots 40 e^{13} and e^{14} , and is under the tension of a retracting-spring e^{15} . The extending arm e^{16} is provided with an L-shaped piece e^{17} , the "vertical-dog" e^{18} , and its retracting-spring e^{19} . The "release-magnet" e^{20} is provided 45 with an armature e^{21} on which are the pivots e^{22} and e^{23} , and which operates against the tension of the retracting-spring e^{24} . The "release-link" e^{25} , on the forward end of which is a slot e^{26} , engages with the "double-dog" e^{27} , by means of a lug e^{28} , said "double-dog" having pivots e^{29} and e^{30} about which it oscillates. It also has a retracting-spring e^{31} and the two angled arms e^{32} and e^{33} , together with the straight arm e^{34} , which 50 latter engages with the link e^{35} . The "rotary-magnet" e^{36} is provided with two magnet-coils e^{37} and e^{38} , which act, when energized, on the armature e^{39} , the latter having pivots e^{40} and e^{41} and being held in its 55 normal position by a retracting-spring e^{42} . On this armature are the usual interrupter-arm e^{43} , the "rotary-armature-finger" e^{44} , and the arm e^{45} that carries the "rotary-pawl" e^{46} with its retracting-spring e^{47} . As 60 shown, e^{48} represents a "private-magnet", its

armature e^{49} being provided with the usual pivots e^{50} and e^{51} , and with the retracting-spring e^{52} . This armature is provided with the arm e^{53} on which is the lateral arm e^{54} , and which has a saw-tooth escapement having teeth e^{55} , e^{56} , e^{57} and e^{58} . The shaft e^{59} has mounted on it the usual set of circular teeth e^{60} slotted at e^{61} to receive the end of the arm or rest e^{62} and the longitudinal teeth e^{63} . On the upper extremity is the coiled spring e^{64} , 70 one end of which is fastened to the pin e^{65} . Just below this spring is the stop-arm e^{66} , while near the lower extremity are the "private-wiper" e^{67} and the "line-wipers" e^{68} and e^{69} , the last two being separated by the insulation e^{70} . Near the middle of the shaft is a cam e^{71} which acts as a stop for the usual "side-switch-arm" e^{72} , and which latter is under the tension of a retracting-spring e^{73} . The stop-lug e^{74} strikes against the said cam; and e^{75} and e^{76} represent the pivots of the "side-switch". On the laterally-projecting arm e^{77} is pivoted the link e^{78} , and just beyond this arm is a shaft e^{79} on which are the usual "side-switch-wipers" e^{80} , e^{81} and e^{82} , which latter engage with the contact-points e^{83} , e^{84} , e^{85} and e^{86} , respectively, when the "side-switch" is in the first position; with contact-points e^{87} , e^{88} , e^{89} and e^{90} when the "side-switch" is in the second 95 position, and with contact-points e^{91} , e^{92} , e^{93} and e^{94} when it is in the third position. In addition to these, e^{96} represents a "back-release-relay" provided with an armature e^{97} . The "connector" may also be of any suitable, known or approved construction, the 100 mechanical details of which are similar to those of the first and second "selectors". In the "connector" are also found the "rotary" and "vertical" "line-relays" f^6 and f^7 , with armatures f^8 and f^9 ; the "vertical-magnet" f^9 with its two coils f^{10} and f^{11} , its armature f^{12} having pivots f^{13} and f^{14} , and retracting-spring f^{15} . On this armature is the arm f^{16} on which is found the L-shaped piece 110 f^{17} —near the middle—and at the end the "vertical-pawl" f^{18} and its retracting-spring f^{19} . There is a "release-magnet" f^{20} having its armature f^{21} provided with pivots f^{22} and f^{23} , and which is operated against the 115 tension of the spring f^{24} . The "release-link" f^{25} is subject to the downward pull of the retracting-spring f^{26} , and said link has at one end an aperture f^{27} , while the other end of said link is fastened permanently to the switch-frame at pin f^{28} . As in the case of the other switches, this "release-link" engages with the "double-dog" f^{29} by means of a lug f^{30} . This "double-dog" 120 has its two pivots f^{31} and f^{32} , and its retracting-spring f^{33} , and is also provided with angled arms f^{34} and f^{35} , and with a straight arm f^{36} , which latter engages with the link f^{37} . There is also the usual "rotary-magnet" f^{38} , composed of coils f^{39} and f^{40} , 125 130

and having the usual armature f^{41} with pivots f^{42} and f^{43} and retracting-spring f^{44} ; the arm f^{45} having at its forward end the "rotary-pawl" f^{46} controlled by a retracting-spring f^{47} . f^{48} represents the private-magnet"; f^{49} the "private-magnet-armature"; and f^{50} and f^{51} its pivots, and f^{52} the arm to which is attached the retracting-spring f^{53} . It has a lateral arm f^{54} and a familiar escutcheon having teeth f^{55} , f^{56} , f^{57} and f^{58} . The usual shaft f^{59} is shown having circular teeth f^{60} provided with a slot f^{61} in which engages the arm or rest f^{62} . Below these circular teeth are the longitudinal teeth f^{63} .

15 On the upper end of the shaft is a coil-spring f^{64} , one end of which is fastened to the stop-post f^{65} , and just below this spring there is a stop-arm f^{66} which engages with the spring f^{67} controlling its contact with the spring f^{68} . On the lower end of this shaft there is the "private-wiper" f^{69} , and still farther down are the "line-wipers" f^{70} and f^{71} separated by insulation f^{72} ; and near the center of this shaft is located the well-known cam f^{73} , which latter controls—at times—the forward movement of the "side-switch-arm" f^{74} , due to the retracting-spring f^{75} , through a lug f^{76} on the "side-switch-arm." This arm has also the pivots f^{77} and f^{78} and the lateral arm f^{79} , on the end of which is pivoted the link f^{80} . To the left of this lateral arm is a shaft f^{80} on which are located the usual "side-switch-wipers" f^{81} , f^{82} , f^{83} and f^{84} which, while the "side-switch" is in its first position, engage with contact-points f^{85} , f^{86} , f^{87} and f^{88} , respectively. When the "side-switch" is in second position, they engage with contact-points f^{89} , f^{90} , f^{91} and f^{92} , respectively; and when the "side-switch" is drawn to its third position, the "side-switch-arm" f^{74} having fallen against stop f^{93} , the respective wipers will then be in contact with the points f^{94} , f^{95} , f^{96} and f^{97} . In addition to these, the bridge-cut-off-relay f^{98} is provided with an armature f^{99} , while the pole-changing-relay f^{100} is provided with an armature f^{101} ; and the differential-coil f^{102} having two windings f^{103} and f^{104} has an armature f^{105} . The ringer-relay is shown at f^{106} , and is provided with an armature f^{107} .

Having thus pointed out the mechanical details of all apparatus, it now remains to trace the circuits. Assuming, to start with, that all switches are in their normal positions, as indicated in Figs. 3, 4 and 5—should the subscriber at the sub-station designated as #6555 (Fig. 1) wish to establish connection with subscriber B of central station #2 (Fig. 2), the number of said called subscriber being #2220, he will first remove his receiver a^2 from its hook a^6 (Fig. 1), then push button a^9 twice and button a^8 once. After this, he will push button a^9 twice and button a^8 once, and again button a^9 twice and button a^8 once; and for the last time, button a^9 ten times and button a^8 once, after which he presses signaling-button a^7 . When the receiver a^2 is removed from its hook a^6 , the latter rises by reason of the pull of a spring. Springs 6 and 7, 8 and 9, 10 and 11 will thereby be closed, the closing of the last two placing the spring 12 directly in contact with the ground at 13 through the following circuit: spring 12, conductors 14 and 15, springs 10 and 11 to ground 13. Now, when button a^9 is pressed twice, thereby causing spring 16 to break contact with spring 17, and to come in contact with spring 12, the said number of times, the "line-conductor" 2 is grounded each time, thereby energizing the "vertical-line-relay" c^5 through the following circuit: from ground 13 to spring 12, to "line-conductor" 2, "side-switch-wiper" c^{84} , contact-point c^{88} , "vertical-line-relay" c^5 , springs 20 and 21, conductors 22 and 24 to non-grounded terminal of battery H^1 to ground h . "Vertical-line-relay" c^5 (Fig. 3) having thus been energized twice, actuates its armature c^6 , which causes springs 25 and 26 to be drawn into contact the same number of times, thereby energizing "vertical-magnet" c^9 (Fig. 3) through the following circuit: ground 27, springs 26 and 25, conductor 28, springs 29 and 30, conductor 31, "vertical-magnet-coils" c^{10} and c^{11} , conductors 32, 33, 34, 35 and 24 to non-grounded terminal of battery H^1 to ground h . When the coils c^{10} and c^{11} of the "vertical-magnet" are thus energized, twice, they attract the armature c^{12} the same number of times. At the first impulse, the armature, by means of the L-shaped piece c^{17} , disengages the "release-link" c^{26} from lug c^{28} , allowing the "double-dog-arms" c^{32} and c^{33} to fall against the circular teeth c^{60} and the longitudinal teeth c^{63} , respectively—due to the tension of the retracting-spring c^{31} . At the same time "vertical-pawl" c^{18} engages with the circular teeth c^{60} , raising the shaft one step; "double-dog-arm" c^{32} dropping underneath the first circular tooth and retaining the shaft in the raised position. The next impulse raises the shaft one more step, in a similar manner, the "double-dog-arm" engaging with the second circular tooth, the "private-wiper" c^{70} having been positioned opposite the first contact of the second row of "private-bank-terminal" c ; "line-wipers" c^{71} and c^{72} also having been raised to a position opposite the first contact of the second row of the "line-bank-terminals" c^2 . Again referring to Fig. 1, when button a^8 is pressed once, spring 35 breaks from contact-point 36 and engages with the ground spring 12, just once, thereby momentarily grounding the "line-conductor" 3, and energizing the "rotary-line-relay" c^7 through the following circuit: from ground 13 at sub-station A to springs 130

12 and 35, to "line-conductor" 3, to "side-switch-wiper" c^{88} , contact-point c^{89} , "rotary-line-relay-coils" c^7 , springs 39, 20 and 21, conductors 22 and 24 to nongrounded terminal of battery H^1 to ground h . "Rotary-line-relay" c^7 (Fig. 3) being thus once energized, causes its armature c^8 to bring springs 40 and 26 (Fig. 3) momentarily together, thereby energizing the "private-magnet" c^{48} through the following circuit: ground 27, springs 26 and 40, conductors 41 and 42, "private-magnet" c^{48} , conductors 43, 35 and 24 to non-grounded terminal of battery H^1 , to ground h . When the "private-magnet" is thus momentarily energized, it actuates its armature c^{49} , only once. As this armature is attracted, "side-switch-arm" c^{75} disengages from tooth c^{56} , falling against tooth c^{56} , and from which latter it in turn disengages when the armature returns to its normal position, striking cam c^{74} , and thus prevented from further advance, for the time being. The "side-switch" has now shifted from its first position, where its wipers c^{82} , c^{83} , c^{84} and c^{85} were in contact with points c^{86} , c^{87} , c^{88} and c^{89} , respectively, into the second position and in contact with the points c^{90} , c^{91} , c^{92} and c^{93} , the arm c^{75} resting between teeth c^{56} and c^{57} . As soon as "side-switch-wiper" c^{82} engages with contact-point c^{90} , the coils c^{87} and c^{88} of "rotary-magnet" c^{89} become energized through a circuit as follows: ground 44, contact-point c^{90} , "side-switch-wiper" c^{82} , conductor 45, "rotary-magnet-coil" c^{88} , springs 46 and 47, "rotary-magnet-coil" c^{87} , conductors 34, 35 and 24 to non-grounded terminal of battery H^1 to ground h . These coils, being energized, attract the "rotary-armature" c^{89} , the "rotary-pawl" c^{46} engaging with the longitudinal teeth c^{63} and rotating the shaft one step, the arm-rest c^{62} now leaving slot c^{61} and engaging with the circular teeth, thereby supporting the shaft during its rotation. As the shaft is rotated, the arm c^{83} of the "double-dog" c^{27} engages with the longitudinal teeth, retaining the shaft in its advanced position and engaging the "private-wiper" c^{70} with the first contact of the second row of "private-bank" C, and the "line-wipers" c^{71} and c^{72} with the first contacts of the second row of "line-bank-terminals" c^2 ; the trunks leading from which latter, it may be assumed, are disengaged at this time. At the same time that "rotary-armature" c^{89} begins to rotate the shaft c^{59} , as explained, the "rotary-armature-finger" c^{44} begins to press the "private-armature" c^{49} toward the pole-piece of the "private-magnet" c^{48} . Now, as soon as the cam c^{74} has been rotated away from the lug c^{77} , the "side-switch-arm" c^{75} falls against the tooth c^{57} , so that by the time that "private-armature" c^{49} strikes the "private-magnet-pole-piece", "side-switch-arm" c^{75}

has become disengaged from said tooth, and has fallen against the tooth c^{58} . By the time this occurs, the interrupter-arm c^{43} on the "rotary-armature" c^{89} has been drawn in far enough to separate springs 46 and 47, thus breaking the circuit that energizes the "rotary-magnet." This will allow the "rotary-armature" to return to its normal position, and the "private-magnet-armature" as well. As soon as this occurs, "side-switch-arm" c^{75} disengages from tooth c^{58} and falls against the stop c^{98} , throwing the "side-switch" into third position. Said "side-switch-wiper" will now be in contact with points c^{94} , c^{95} , c^{96} and c^{97} . The subscribers' "line-conductors" 2 and 3 (Fig. 3) are now extended by and along the bank-trunk-line as follows: subscriber's "vertical-line-conductor" 2, "side-switch-wiper" c^{84} , contact-point c^{96} , conductor 48, "vertical-line-wiper" c^{71} , trunk-line-conductor similar to c^8 to a disengaged repeater, back to a trunk-line-conductor similar to c^4 , "rotary-line-wiper" c^{72} , conductor 49, contact-point c^{97} , "side-switch-wiper" c^{85} and "rotary-line-conductor" 3. "Side-switch-wiper" c^{88} being in the third position and, therefore, engaged with contact-point c^{95} , places "private-wiper" c^{70} , and, therefore, the "private-bank-contact" with which it is engaged, in connection with ground, and with the grounded terminal of the battery H^1 through the following path: from battery H^1 to ground h , to "side-switch-ground" 50, contact-point c^{95} , "side-switch-wiper" c^{88} , conductor 51, "back-release-relay" c^{101} , conductor 52, "private-wiper" c^{70} to engaged contact. This establishes a guarding potential on the first contact of the second row of "private-bank-terminals" c , so as to prevent another subscriber from coming in on the same line, in a manner that will be hereafter explained. Returning to that stage of the call before subscriber #6555 (Fig. 1) had pressed the button a^8 once: The shaft c^{59} had been raised two steps, and the "private-wiper" c^{70} had been brought opposite the first contact of the second row of "private-bank" c ; while the "line-wipers" c^{71} and c^{72} had been brought opposite contacts of the second row of "line-bank-terminals" c^2 . Now assume that the first nine trunks or trunk-lines of the second level are in use by nine "first-selectors" all similar to the "selector" shown in Fig. 3. The switch using the first trunk of the second level will have its "private-wiper" engaging the first contact of the second row of its "private-bank" similar to "private-bank" c ; also, "side-switch" of said occupying "selector" is in third position, having a wiper, similar to the "side-switch-wiper" c^{88} , engaging with the contact-point similar to c^{95} . This places the first contact of the second row in connection with the

grounded terminal or battery H^1 , through a circuit similar to the one already explained in connection with the "first-selector" of Fig. 3; a guarding potential being, therefore, established. The same will be the case with the other eight busy trunks. Now, if subscriber #6555 (Fig. 1) presses the button a^8 once, he will momentarily energize the "rotary-line-relay" c^7 (Fig. 3) through a circuit already described, causing the "private-magnet" c^{48} to be energized as before. The "private-armature" c^{49} , being attracted, disengages the "side-switch-arm" c^{75} from the tooth c^{55} , allowing it to fall against tooth c^{56} , and from which latter it in turn disengages as soon as the armature returns to its normal position; the "side-switch" being, therefore, brought to the second position, and "side-switch-wiper" c^{82} coming in contact with grounded terminal c^{90} , as previously explained. The coils c^{37} and c^{38} of the "rotary-magnet" c^{36} will now be energized, attracting the armature c^{39} and rotating shaft c^{59} one step in the manner already described, and thus rotating the "private-wiper" c^{70} and engaging it with the first contact of the second row of "private-bank" c ; "line-wipers" c^{71} and c^{72} being likewise "cut-in" on the first contact of the second row of "line-bank-terminals" c^2 . Owing to the guarding potential which has already been described, existing on said first contact as soon as the "private-wiper" c^{70} engages with the first contact, and before the "rotary-armature" c^{39} has begun to return to its normal position, the "private-magnet" c^{48} is energized through the following circuit: from non-grounded terminal of battery H^1 to conductors 24, 35 and 43, "private-magnet" c^{48} , conductors 42 and 53, contact-point c^{91} , "side-switch-wiper" c^{83} , conductor 51, "back-release-relay" c^{101} , conductor 52, "private-wiper" c^{70} to the first contact of the second row of "private-bank" c , through an occupying switch (not shown) to ground h , to battery H^1 . Thus energized, "private-magnet" c^{48} attracts its armature c^{46} , and relieves the "rotary-armature-finger" c^{44} of its care of said armature, "side-switch-arm" c^{75} now disengaging with tooth c^{57} and falling upon tooth c^{58} . As soon as the "rotary-armature" c^{39} rotates the shaft one step, the interrupter-arm c^{43} separates springs 46 and 47, thus deenergizing the "rotary-magnet" c^{48} ; "rotary-armature" c^{39} returning to its normal position. It will be noticed, however, that the "private-armature" c^{49} is still held down, due to the circuit established through "private-magnet" c^{48} , and owing to the guarding potential on the first "private-contact" of the second level of "private-bank-terminal" c . As soon as the "rotary-armature" has returned to its normal position, the interrupter-springs 46 and 47 again resume contact with each other, again energizing "rotary-magnet" c^{48} through the same circuit as before. The "rotary-armature" will again be attracted, rotating the shaft one more step, and thereby bringing the "private-wiper" onto the second contact of the second level of "private-bank" c . As it has been assumed that this contact also has a guarding potential, the "private-armature" c^{49} will still be held down. As soon as the interrupter-arm c^{43} again separates the interrupter-springs 46 and 47, the "rotary-armature" will fall back once more, allowing said springs to again engage each other. This will be repeated as often as "private-wiper" c^{70} encounters contact-points having guarding potential. When the shaft has been rotated nine steps, the "private-wiper" will then be found in engagement with the ninth contact of the second level, but which contact is also busy, as previously stated. The "rotary-magnet" will be energized once more, and the shaft will be rotated one more step, at last placing the "private-wiper" c^{70} , as well as "line-wipers" c^{71} and c^{72} , on the tenth contact of their respective banks. As soon as the "private-wiper" leaves the ninth contact, the circuit through the "private-magnet" is broken, there being no guarding potential on the tenth contact; "private-armature" c^{49} is restored to the charge of "rotary-armature-finger" c^{44} , immediately after which the circuit through the "rotary-magnet" is broken for the last time by interrupter-arm c^{43} ; and the "rotary-armature" will then fall back to its normal position, as well as the "private-armature", when the "side-switch-arm" c^{75} will disengage from the last tooth c^{58} , falling against stop c^{98} and bringing the "side-switch" to its third position, as before. At this time, the subscribers' "line-conductors" 2 and 3 are extended to a disengaged repeater through trunk-line-conductors 3 and 4, clearly shown in Fig. 1. Guarding potential is now established at the tenth contact of the second level of "private-bank" c , by the "side-switch-wiper" c^{83} again engaging with grounded contact-point c^{95} , thus preventing anyone from cutting in on this trunk while it is in use. It will be noticed that while "private-wiper" c^{70} was passing over the contacts that have guarding potential—that is, which are temporarily connected with the grounded or positive pole of the battery—the "private-magnet" was energized through a circuit which included the "back-release-relay" c^{101} ; but this relay is of such low resistance as not to interfere with the working of the private-magnet" c^{48} ; and at the same time, the "private-magnet-coil" is of such comparatively high resistance that the energizing current, when they are both in series, is not strong enough to draw down the armature c^{102} against the tension of spring 54. The subscriber has

now extended his line to and over trunk-line-conductors c^3 and c^4 , as already explained. The shifting of the "side-switch" into the third position not only extends the 5 subscribers' lines, but disconnects the "selector" from the main "line-conductor" 2 and 3 at the instant the "side-switch-wipers" c^{84} and c^{85} leave the contact-points c^{92} and c^{93} , as is clearly shown in Fig. 1 or 10 Fig. 3. The calling subscriber, having thus extended the lines to a disengaged repeater (as clearly shown in Fig. 1), again presses his button a^9 twice, thus again grounding the "vertical-line-conductor" 2 by bringing 15 it in contact with spring 12, as before, and thereby energizing "vertical-line-relay" d at repeater D twice as follows: from ground 13 at sub-station #6555, to ground-spring 12, "line-conductor" 2, switching-arm c^{84} , 20 wiper c^{71} , "vertical-trunk-conductor" c^8 , "vertical-line-relay" d , winding d^6 of differential-relay d^5 , springs 54 and 55, conductor 56 to battery H^1 , and to ground h . Thus energized, "vertical-line-relay" d activates 25 its armature d^4 , bringing springs 56 and 57 together twice, grounding "vertical-normal trunk-line-conductor" 4 the same number of times, as follows: from ground 58 at the repeater, through springs 59 and 30 60, conductor 61, springs 57 and 56, conductor 62, springs 63 and 64 to "vertical-trunk-line" 4. The effect of the grounding of this conductor will be explained. The current that energizes "vertical-line-relay" d 35 passes through winding d^6 of the differential-relay d^5 , thereby energizing said differential-relay with the result that its armature d^8 is attracted and contact thereby broken between spring 66 and contact-point 40 67. The separating of this spring from this contact opens a bridge between the "vertical-trunk-conductor" 4 and "rotary-trunk-conductor" 5, which is ordinarily closed as follows: from "vertical-trunk-conductor" 4 to conductor 65, to contact-point 67, spring 66, relay d^9 to conductor 68 and to "rotary-trunk-conductor" 5. In this way, the "rotary-trunk-conductor" 5 is prevented from being grounded 45 through coil d^9 at the same time that "vertical-trunk-conductor" 4 is grounded by the actuation of relay-armature d^1 . After pressing button a^9 , button a^8 is pressed once, thus grounding "line-conductor" 3, momentarily, with spring 12, thereby energizing "rotary-line-relay" d^3 at repeater D, momentarily, through the following circuit: from ground 13 at sub-station #6555 to springs 12 and 35, to 50 "line-conductor" 3, switching-arm c^{86} , wiper c^{72} , conductor c^4 , "rotary-line-relay" d^3 , winding d^7 of differential-coil d^5 , conductor 56 to battery H^1 and to ground h . "Rotary-line-relay" d^3 , thus energized once, actuates 55 its armature d^4 , which closes springs 69 and

57, thereby grounding "rotary-trunk-conductor" 5. The same current that energizes "rotary-line-relay" d^3 passes through winding d^7 of the differential-relay d^5 , thereby energizing it; and the armature d^8 being 60 attracted, contact is again broken between spring 66 and contact-point 67, thereby again opening the bridge between trunk-conductors 4 and 5. This prevents conductor 4 from being grounded at the same 65 time with trunk-conductor 5 each time that the "rotary-relay-armature" d^4 is actuated. Referring to Fig. 4, when "vertical-trunk-conductor" 4 is grounded twice, momentarily, as above explained, by the calling 70 subscriber at sub-station #6555, by pressing button a^9 twice, the second time, "vertical-line-relay" e^5 is energized twice, as follows: from ground at the repeater to "vertical-trunk-conductor" 4, as already 75 explained, to "side-switch-wiper" e^{81} , to contact-point e^{85} , conductor 70, "vertical-line-relay" e^5 , conductors 71 and 72 to non-grounded terminal of battery H^2 , and to ground h^1 . "Vertical-line-relay" e^5 being 80 thus energized, its armature e^6 causes springs 73 and 74 to come together, thereby energizing the coils e^{10} and e^{11} of "vertical-magnet" e^9 through the following circuit: from ground 75 to springs 74 and 73, conductor 85 76, springs 77 and 78, conductor 79, "rotary-magnet-coils" e^{10} and e^{11} , conductors 80, 82 and 72 to non-grounded terminal of battery H^2 , and to ground h^1 . Thus energized, the "vertical-magnet" e^9 actuates its armature 90 e^{12} twice. As in the case of the "first-selector", this armature engages with the circular teeth e^{60} on the shaft e^{59} , raising the latter two steps. At the first impulse of armature e^{12} , the "release-link" e^{25} disengages from lug e^{28} on the "double-dog" e^{27} , allowing the arms e^{32} and e^{33} of said "double-dog", respectively, to fall against the circular and longitudinal teeth e^{60} and e^{63} . The arm e^{32} , by engaging with the circular 95 teeth, holds the shaft in its raised position. The shaft having been raised two steps, the "private-wiper" e^{67} on this shaft is brought to the level of the first contact of the second level or row of "private-bank" e , while 100 the "line-wipers" e^{68} and e^{69} are brought to the level of the first contacts or terminals of the second level of "line-bank" e^2 . Now, when the "rotary-trunk-conductor" 5 is 105 grounded once at the repeater D, as was shown, the "rotary-line-relay" e^7 (Fig. 4) is energized once as follows: from ground at the repeater to "vertical-trunk-conductor" 5, through "side-switch-arm" e^{82} , contact-point e^{86} , conductor 83, "rotary-line-relay" 110 e^7 , conductors 71 and 72 to non-grounded terminal of battery H^2 , and to ground h^1 . Thus momentarily energized, the "rotary-line-relay" e^7 actuates its armature e^8 , causing springs 84 and 74 to come together, thus 115 120 125 130

energizing "private-magnet" e^{48} through the following circuit: from ground 75 to springs 74 and 84, conductors 85 and 86, "private-magnet" e^{48} , conductors 87, 82 and 72 to 5 non-grounded terminal of battery H^2 and to ground h^1 . When the "private-magnet" e^{48} is thus momentarily energized, it attracts its armature e^{49} once. As this armature is attracted, the "side-switch-arm" e^{72} disengages from tooth e^{55} and falls against tooth e^{56} , but from which it in turn disengages as soon as the armature returns to its normal position, thereby placing the "side-switch" in second position. The "side-switch-wipers" e^{70} , e^{80} , e^{81} and e^{82} having changed contact from points e^{83} , e^{84} , e^{85} and e^{86} to points e^{87} , e^{88} , e^{89} and e^{90} , respectively, any further advance of said "side-switch" is checked by the lug e^{74} on the "side-switch-arm" e^{72} striking against the cam e^{71} . "Side-switch-wiper" e^{79} having engaged with contact-point e^{87} , the coils e^{37} and e^{38} of "rotary-magnet" e^{38} become energized through a circuit identically the same as that previously 25 described in the "first-selector". These coils, being energized attract their armature e^{39} , causing the shaft e^{59} to rotate. Presuming that the first nine trunks of the second level are all busy, guarding potential will be 30 found at the first nine contacts of the second row of "private-bank" e . As soon as "private-wiper" e^{67} engages with the first contacts, the "private-magnet" e^{48} will be energized, as in the "first-selector", attracting 35 its armature e^{49} and thereby causing said "side-switch-arm" e^{72} to disengage with tooth e^{57} , and to fall against tooth e^{58} , holding the "side-switch" in its second position. The "side-switch-wiper" e^{79} is now in contact with the grounded point e^{87} , and "side-switch-wiper" e^{80} in contact with point e^{88} . As long as "side-switch-wiper" e^{79} remains in contact with point e^{87} , the "rotary-magnet" e^{38} will be energized, interruptedly, 40 thus giving the shaft e^{59} a step-by-step rotary motion until the "private-wiper" e^{67} is rotated onto some contact that has no guarding potential, as has already been explained in connection with the "first-selector". At that moment, the "private-magnet" e^{48} becomes deenergized, restoring 45 its armature to the care of the finger e^{44} , which, with the "rotary-armature" which is returning to its normal position for the last 50 time, allows the "private-armature" e^{49} to also return to its normal position, thereby allowing the "side-switch-arm" e^{72} to disengage from the last tooth e^{58} . This throws the "side-switch" into its third position, thus 55 causing the "side-switch-wipers" e^{70} , e^{80} , e^{81} and e^{82} to close with contact-points e^{92} , e^{93} , e^{94} and e^{95} , extending the subscribers' "line-conductors" 4 and 5 along disengaged conductors e^8 and e^4 to a "connector" not in 60 use, as follows: from "vertical-conductor" 4 65 to "side-switch" e^{81} , contact-point e^{94} , conductor 88, "vertical-line-wiper" e^{68} , "vertical-trunk-conductor" e^3 , through the "connector" and back through the "rotary-trunk-conductor" e^4 , "rotary-line-wiper" e^{69} , 70 conductor 89, contact-point e^{95} and "side-switch-wiper" e^{82} to "rotary-conductor" 5. In the "second-selector", as in the first, as soon as the "side-switch" passes to the third position, the switch is cut off from 75 the main "line-conductors" 4 and 5, the release of the switch depending on the "private-trunk-line" with which the "private-wiper" e^{67} engages, as will hereinafter be demonstrated. "Side-switch-wiper" e^{80} having engaged with contact-point e^{83} , a guarding potential is established on the tenth contact of the second row or level of "private-bank-terminal" e , with which "private-wiper" e^{67} is engaged through the following: 80 circuit from battery H^2 to ground h^1 , to ground 90 at the "side-switch", contact-point e^{83} , "side-switch-wiper" e^{80} , conductor 91, "back-release-relay" e^{96} , conductor 92, "private-wiper" e^{67} to tenth contact of second row 90 or level of "private-bank" e . The next act of the calling subscriber #6555 (Fig. 1) is to press the button a^9 twice, again twice grounding subscriber's "line-conductor" 2, thus energizing the "vertical-line-relay" d 95 twice, and winding d^6 of differential-relay d^5 the same number of times. "Vertical-line-relay" d , being thus energized, actuates its armature d^1 twice, which grounds "vertical-trunk-conductor" 4 twice, in a manner 100 already explained. The grounding of "vertical-trunk-conductor" 4 energizes "vertical-line-relay" f^5 of "connector" F (Fig. 2), over the following circuit: from ground 58 at repeater D (Fig. 1) through springs 59 105 and 60, conductor 61, springs 57 and 56, conductor 62, springs 63 and 64 to "vertical-trunk-conductor" 4 (Fig. 2), switching-arm e^{81} , wiper e^{68} , conductor e^3 , "vertical-line-relay" f^5 , winding f^{103} of differential-coil 110 f^{102} , springs 95 and 96, conductor 97 to non-grounded terminal of battery H^2 , and to ground h^1 . The energizing of "vertical-line-relay" f^5 (Fig. 5), twice, causes its armature f^6 to be actuated twice, bringing 115 springs 99 and 100 together, thereby energizing coils f^{10} and f^{11} of "vertical-magnet" f^9 through the following circuit: from ground 101 to springs 99 and 100, conductor 102, springs 103 and 104, 120 conductor 105, "side-switch-arm" f^{81} , contact point f^{85} , coils f^{11} and f^{10} of the "vertical-magnet", conductor 106, conductor 107, springs 108, 109 and 110, conductor 97 and 98 to the non-grounded terminal of battery 125 H^2 , and to ground h^1 . Thus energized, on the first impulse the "vertical-magnets" f^9 actuates its "vertical-armature" f^{12} , the "vertical-dog" f^{18} engaging with the circular teeth f^{60} on the shaft f^{59} , and raising 130

the shaft one notch. At the same time, the L-shaped piece f^{17} disengages the "release-link" f^{25} from the lug f^{30} on the "double-dog" f^{29} , allowing the arm f^{34} on the latter 5 to drop into engagement with the circular teeth f^{60} , under the tension of the retracting-spring f^{33} , to retain the shaft in its raised position. On the second impulse, the "vertical-pawl" f^{18} again engages the circular 10 teeth, raising the shaft one more notch and bringing the "private-wiper" f^{69} on the said shaft to a level with the first contact of the second row of "private-bank-terminals" f , and the "rotary" and "vertical" "line-wipers" f^{70} and f^{71} , also on said shaft, opposite the first contact of the second row or level of "line-bank-terminals" f^2 . In the next step, the subscriber #6555 (Fig. 1) presses the button a^8 once, momentarily, 15 thus grounding "line-conductor" 3 by bringing it into contact with the grounded spring 12, thus energizing the "rotary-line-relay" d^3 and differential-relay d^5 , as already explained. Thus energized, the "rotary-line-relay" d^3 actuates its armature, which grounds the "rotary-trunk-line-conductor" 5, thereby energizing the "rotary-line-relay" of "connector" F in Fig. 2, as 20 follows: from ground 58 at repeater D to springs 59 and 60, conductor 61, springs 57 and 69, conductor 169, "rotary-trunk-conductor" 5, switching-arm e^{82} , (Fig. 2), wiper e^{69} , trunk-conductor e^4 , "rotary-line-relay" f^7 , winding f^{104} of differential-coil 25 f^{102} , conductor, 97 to non-grounded terminal of battery H^2 , and to ground h^1 . The "rotary-line-relay" f^7 , having thus been energized once, actuates its armature f^8 (Fig. 5), causing springs 23 and 99 to come 30 together. A circuit is thereby closed which energizes the "private-magnet" f^{48} as follows: from ground 101 to springs 99 and 23, conductor 112, "private-magnet" f^{48} , conductor 113, springs 109 and 110, conductors 97 and 98 to the non-grounded terminal of battery H^2 , to ground h^1 . Thus energized, "private-magnet" f^{48} actuates its armature f^{49} . When the "private-armature" 35 is attracted, the "side-switch-arm" f^{74} disengages from tooth f^{65} , coming into contact with tooth f^{56} , from which latter it disengages when the "private-armature" regains its normal position, under the tension of the retracting-spring f^{53} . The "side-switch" 40 is, therefore, moved to second position, the "side-switch-wipers" f^{81} , f^{82} , f^{83} and f^{84} breaking with contact-points f^{85} , f^{86} , f^{87} and f^{88} , and closing with contact-points f^{89} , f^{90} , f^{91} and f^{92} , respectively. The next operation 45 on the part of subscriber #6555 (Fig. 1) is to press the button a^9 ten times, for the last time, again energizing the "vertical-line-relay" d at repeater D, as well as the differential-coil d^5 , each ten times. The 50 energizing of "vertical-line-relay" d at re-

peater D again energizes the "vertical-line-relay" f^5 ten times (Fig. 2)—of "connector" F—through the same circuit as before. Referring to Fig. 5, the energizing of the "vertical-line-relay" f^5 actuates its armature f^6 ten times, energizing in turn coils f^{39} and f^{40} of "rotary-magnet" f^{38} ten times, through the following circuit: from ground 101 to springs 99 and 100, conductor 102, springs 103 and 104, conductor 105, "side-switch-arm" f^{81} , contact-point f^{89} , coils f^{39} and f^{40} of "rotary-magnet" f^{38} , conductors 106 and 107, springs 108, 109 and 110, conductors 97 and 98 to non-grounded terminal of battery H^2 , and to ground h^1 . Each 55 time the "rotary-armature" is attracted, the "rotary-pawl" f^{46} engages with the longitudinal teeth f^{63} , rotating the shaft one step against the tension of the coil-spring f^{64} , and held in place at each step by arm f^{35} of the "double-dog" f^{29} . At the end of this 60 operation, the "line-wipers" f^{70} and f^{71} , as well as "private-wiper" f^{69} , will be found on the tenth contact of the second row of their respective banks f^2 and f , the trunks 65 leading from which are, it may be assumed, disengaged. The next act of the calling subscriber #6555 is to press the button a^8 once, for the last time, again momentarily grounding the "rotary-line-conductor" 3, 70 thereby energizing the "rotary-line-relay" d^3 and differential-relay d^5 at repeater D, which in turn energizes the "rotary-line-relay" f^7 (Fig. 2) of "connector" F through a circuit as before. "Rotary-line-relay" f^7 75 (Fig. 5), thus energized, again actuates its armature f^8 , energizing "private-magnet" f^{48} as before. The "private-magnet" f^{48} being thus energized once, actuates its armature once. This causes "side-switch-arm" 80 f^{74} to disengage from tooth f^{67} on the downward stroke, and to fall against tooth f^{58} . Said arm in turn disengages from the last tooth on return to normal position, and falls 85 against stop f^{93} . This throws the "side-switch-wipers" f^{81} , f^{82} , f^{83} and f^{84} into contact with points f^{94} , f^{95} , f^{96} and f^{97} , respectively. This final operation will connect the calling subscriber with the called subscriber, through the normal-trunks f^3 and 90 f^4 , as follows: from "vertical-line-conductor" 2 (Fig. 1) to switching-arm e^{84} , conductor 48, wiper e^{71} , conductor e^3 , condenser d^{12} to conductor 4 (Fig. 2), switching-arm e^{81} , wiper e^{68} , conductor e^8 , condenser f^{108} , 95 thence to conductor 114 and to springs 115 and 116 to switching-arm f^{83} , contact-point f^{96} , wiper f^{70} , conductor f^3 , conductor 117, spring 118, contact-point 119, conductor 120 to hook b , to spring 121, ringer 122, conductor 123, condenser b^1 , conductor 124, contact-point 125, spring 126, conductors 127 and f^4 , wiper f^{71} , contact-point f^{97} , switching-arm f^{84} , springs 128 and 129, conductor 130, condenser f^{109} , thence to conduct- 100 105 110 115 120 125 130

tor e^4 , switching-arm e^{80} , switching-arm e^{82} , "rotary-trunk-conductor" 5 (Fig. 1), condenser d^{13} , wiper c^{72} , conductor 49, switching-arm c^{85} , "rotary-line-conductor" 3, 5 spring 35, contact-point 36, condenser a^5 , secondary winding 131 of induction-coil a^4 , conductor 132, receiver a^2 , conductor 133, springs 7 and 6, conductor 134, contact-point 17 to spring 16 and to conductor 2 again. In Fig. 5, as soon as the "side-switch" comes into third position, the "side-switch-wiper" f^{82} comes in contact with grounded point f^{95} , establishing a guarding potential at the "private-bank-contact" with 10 which "private-wiper" f^{90} is engaged, as well as at all other "private-contacts" with which it is connected in multiple—in this case being the tenth contact in the second row or level. This circuit is as follows: 15 from battery H^2 to ground h^1 , "side-switch-ground" 135 to contact-point f^{95} , to "side-switch-wiper" f^{82} , conductor 202, conductor 136 to "private-wiper" f^{60} and to tenth contact of the second row or level of "private-bank" f , thus protecting the line against 20 intrusion. Referring to Fig. 2: At the same time the guarding potential is established at the tenth contact of the second row or level of "private-bank" f , a circuit is established by way of said contact along the "private-normal" f^1 , which energizes the so-called bridge-cut-off-relay g of the called subscriber's "first-selector-switch", through 25 the following circuit: from ground 135 of "connector" F, to switching-arm f^{82} , conductor 136, wiper f^{60} , conductor f^1 , spring 137, contact-point 138, bridge-cut-off-relay g , conductor 139 to battery H^2 , and to ground h^1 . Thus energized, bridge-cut-off- 30 relay-magnet g attracts its armature g^1 , separating springs 140, 141 and 142, thus cutting off the bridge formed by "line-relays" g^2 and g^3 across lines f^3 and f^4 and ordinarily closed through the following circuit: conductor f^3 , switching-arm g^4 , "vertical-line-relay" g^2 , springs 141 and 142, "rotary-line-relay" g^3 , switching-arm g^5 to conductor f^4 . The object of opening this bridge is twofold and will be referred to later on. 35 The operator at the sub-station #6555 (Fig. 1) is now ready to ring the bell at sub-station #2220 (Figs. 1 and 2). He presses button a^7 , which will cause the spring 143 to break away from the contact 144, and 40 close with contact 145. This will energize the "vertical-line-relay" d at repeater D, through the following circuit: from ground 13 at the calling subscriber's station #6555 to springs 11 and 10, to contact-point 145, to spring 143, through springs 8 and 9 and 7 and 6 to contact-point 17, to spring 16, thence to "vertical-line-conductor" 2, through "vertical-line-relay" d at repeater D and differential- 45 relay d^6 , and to the non-grounded terminal of the battery H^1 , as before. Thus energized, the "vertical-line-relay" d actuates its armature d^1 , which in turn grounds the "vertical-trunk-conductor" 4, thus energizing "vertical-line-relay" f^5 of "connector" F, through 50 the well-known circuit: The "vertical-line-relay" f^5 then actuates its armature f^6 , which closes contact between springs 99 and 100, thus energizing ringer-relay f^{106} , as follows: from ground 101 to springs 99 and 100 and 55 to springs 103 and 104, conductor 105, "side-switch-wiper" f^{81} , contact-point f^{94} , conductor 146 to ringer-relay f^{106} , conductors 147 and 107, springs 108, 109 and 110, thence to conductor 97, and to the non-grounded 60 terminal of the battery H^2 to ground h^1 . Thus energized, ringer-relay f^{106} attracts its armature f^{107} , thereby separating spring 128 from 129, and bringing it into contact with spring 148; also, spring 116 from 115, bringing 65 it into contact with 149. Springs 115 and 129 constitute the terminals of the sub-station #6555, and springs 116 and 128 the terminals of the sub-station #2220; while springs 148 and 149 constitute the terminals 70 of the ringer machine N. It is evident that the function of the ringer-relay f^{106} is to separate the line of subscriber #2220 from the line of subscriber #6555, and to close it with the terminals of generator N as long as 75 subscriber #6555 is pressing button a^7 . In this way, the ringer or bell or signaling apparatus 122 at sub-station #2220 is energized through the following circuit: from generator N to conductors 150 and 151, 80 springs 149 and 116, switching-arm f^{83} , contact-point f^{96} , wiper f^{70} conductor f^3 , conductor 117, spring 118, contact-point 119, conductor 120, hook b , spring 121, ringer or bell 122, conductor 123, condenser b^1 , conductor 124, contact-point 125, spring 126, conductors 127 and f^4 , wiper f^{71} , contact-point f^{97} , switching-arm f^{84} , springs 128 and 148 to conductors 152 and 153 and to generator N. The bell 122 at sub-station #2220 85 will now ring until the subscriber at #6555 releases button a^7 , thereby allowing the "vertical-line-relay" d at repeater D, and "vertical-line-relay" f^5 at "connector" F, and ringer-relay f^{106} , to resume their normal 90 positions. Springs 128 and 116 again falling back upon springs 129 and 115, respectively, reestablish connection between sub-station #6555 and #2220. It will be noticed that heretofore as "line-relays" f^1 95 and f^5 , respectively, have been energized, the energizing current has in each case passed through one winding of the differential-relay f^{102} , thus energizing it and thereby actuating its armature; but up to the present time this has had no significance. Had not bridge-cut-off-relay g (Fig. 2) on the called subscriber's "first-selector" G opened the bridge across lines f^3 and f^4 , the ringing current would have passed through the 100

bridging "rotary" and "vertical" "line-relays" g^2 and g^3 , energizing them and making it possible for the shaft of switch G to be raised "off-normal" because of the actuation 5 of their armatures g^6 and g^7 , thus grounding springs 154 and 155 against spring 156, as in the "first-selector" G, thereby actuating the "rotary" and "vertical" magnets, which would interfere with the connection. It is 10 obvious that during conversation, and while voice currents are passing over conductors f^3 and f^4 , it is desirable that this bridge be open. When subscriber at sub-station #2220 answers by removing his receiver b^3 from hook b , the ringer circuit will be opened at the junction of switch-hook b with spring 151. At the same time the following springs will be closed: 157 and 158; 159 and 160; and 161 and 162. Talking current will now 15 be established on the lines of the substation #2220, through its transmitter b^4 and the primary winding of the induction-coil b^5 , which current energizes the magnet-cut-off-relay f^{98} and pole-changing-relay f^{100} , 20 through the following circuit: from ground 135 at "connector" F, to switching-arm f^{82} , spring 165, contact-point 164, magnet-cut-off-relay f^{98} , conductor 114, springs 115 and 116, switching-arm f^{83} , contact-point f^{96} , 25 wiper f^{70} , conductors f^5 and 117, spring 118, contact-point 119, conductor 120, springs 158 and 157, springs 160 and 159, transmitter b^4 , primary winding 163 of induction-coil b^5 , conductor 124, contact-point 125, spring 30 126, "line-conductor" 127, conductor f^4 , wiper f^{71} , contact-point f^{97} , switching-arm f^{84} , springs 128 and 129, conductor 130, pole-changing-relay f^{100} to the non-grounded terminal of the battery H^2 , to ground h^1 . 35 Thus current for talking purposes is furnished from the common battery H^2 to transmitter b^4 , primary winding 163 of induction-coil b^5 , through the magnet-cut-off-relay f^{98} and pole-changing-relay f^{100} . 40 When the latter becomes energized, its armature f^{101} is attracted, causing spring 95 to break with spring 96, and to engage with spring 166, thereby energizing a circuit which contains both windings of the differential-relay f^{102} , "vertical" and "rotary" 45 "line-relays" f^5 and f^7 at the "connector" F, and a bridge-cut-off-pole-changing-relay d^9 at the repeater D (Fig. 1). The circuit is as follows: from ground 167 at "connector" F to springs 166 and 95 to winding f^{103} 50 of differential-relay f^{102} , "vertical-line-relay" f^5 , conductor e^8 , wiper e^{68} , conductor 88, switching-arm e^{81} , "vertical-trunk-conductor" 4 (Fig. 1), conductor 65, contact-point 55 67, spring 66, bridge-cut-off pole-changing-relay d^9 , conductor 68, "rotary-trunk-conductor" 5 (Fig. 2), switching arm e^{82} , conductor 89, wiper e^{69} , conductor e^4 , "rotary-line-relay" f^7 , "connector" F, winding f^{104} of the 60 differential-relay f^{102} , conductor 97 to the 65 non-grounded terminal of battery H^2 , and to ground h^1 . This current, passing through both windings of the differential-relay f^{102} , 70 does so in such a manner that the magnetic effects are neutralized; but both the "rotary" and the "vertical" "line-relays" f^7 and f^5 become energized, thereby attracting their armatures and grounding springs 100 and 23 by bringing them into contact with the spring 99. Magnet-cut-off-relay f^{98} being 75 energized, however, at the same time, attracts its armature f^{99} , thereby separating springs 108, 109 and 110 for the purpose of rendering the following magnets inoperative; ringing-relay f^{106} , "private-magnet" f^{48} 80 and "release-magnet" f^{20} . It is not desirable that these magnets be energized at this stage by the actuation of armatures f^6 and f^8 of the "vertical" and "rotary" "line-relays" f^7 and f^5 . At the same time that 85 these last relays are energized, bridge-cut-off pole-changing-relay d^9 at the repeater D becomes energized, actuating its armature d^{10} , thereby causing spring 54 to separate from spring 55 and to close contact with 90 spring 59; spring 60 to separate from spring 59; and spring 64 to separate from spring 63. As soon as contact closes between springs 54 and 59, talking current is 95 furnished to the calling subscriber's line through the two windings of the differential-relay d^5 , "vertical" and "rotary" "line-relays" d and d^8 , the primary winding of induction-coil a^4 , and the transmitter a^8 at sub-station A, through the following circuit: 100 from ground 58 at repeater D (Fig. 1) to springs 59 and 54, winding d^6 of differential-coil d^5 , "vertical-line-relay" d , conductor c^8 , wiper c^{71} , conductor 48, switching-arm c^{84} , conductor 2, spring 16, contact-point 17, conductor 134, springs 6 and 7, 105 springs 9 and 8, to spring 143, to contact-point 144, to transmitter a^8 , primary winding 168 of induction-coil a^4 , conductor 169, contact-point 36, spring 35, conductor 3, 110 switching-arm c^{85} , conductor 49, wiper c^{72} , conductor c^4 , "rotary-line-relay" d^3 and winding d^7 of the differential-coil d^5 , conductor 56 to non-grounded terminal of battery H^1 , and to ground h . This talking current, 115 as in the case of a "connector," passes through both windings of the differential-coil d^5 in such a manner that the magnetic effects are neutralized; but the "rotary" and "vertical" relays d and d^8 become energized, 120 attracting their armatures d^4 and d^8 thereby closing springs 69 and 56^a onto spring 57. The closing of these springs at this stage has no significance, as the armature d^{10} of the bridge-cut-off pole-changing-relay d^9 125 keeps springs 59 and 60 apart, as already stated, thereby maintaining an open connection to ground. We see, therefore, referring to Figs. 1 and 2, that when the called subscriber at sub-station #2220 re- 130

moves his receiver from its hook, talking battery current is furnished to his line, which energizes the pole-changing-relay f^{100} at the "connector" F. Among other things, the energizing of this relay in turn causes the bridge-cut-off pole-changing-relay at the repeater D to be energized, causing spring 54 to break from spring 55 and to close with spring 59, thus furnishing talking battery current to the calling subscriber's line. Referring again to the repeater D, when the armature d^{10} of the bridge-cut-off pole-changing-relay d^0 is actuated, it was stated that spring 64 broke contact with spring 63. This opens up a bridge between conductors 4 and 5, which, when springs 56^a, 57 and 69 are kept in contact by armatures d^1 and d^4 , would ordinarily be closed as follows: conductor 4 to springs 64 and 63, conductor 62, springs 56^a, 57 and 69 to conductors 169 and 5. It is obvious that this bridge, which amounts to a short-circuit, is not desirable, conductors 4 and 5 being, as will be seen, part of the main talking lines. Talking current having thus been furnished to the calling and the called subscribers' stations, when operator at sub-station #2220 speaks into transmitter b^4 , the resistance of the circuit through which talking current passes is varied, thereby causing the current to vary similarly. In this talking current, as has been stated, there is included the primary winding 163 of induction-coil b^5 . Variations in the intensity of the talking current induce currents in turn in the secondary winding 170 of induction-coil b^5 in the usual way, which reach receiver a^2 at the substation A through the following circuit: from the secondary winding of induction-coil b^5 at sub-station #2220 to conductor 171 to receiver b^3 , conductor 172, springs 157 and 158, conductor 120, contact-point 119, spring 118, conductors 117 and f^8 , wiper f^{10} , contact-point f^{100} , switching-arm f^{83} , springs 116 and 115, conductor 114, condenser f^{108} , conductor e^3 , wiper e^{68} , conductor 88, switching-arm e^{81} , "vertical-trunk-conductor" 4 (Fig. 2), "vertical-trunk-conductor" 4 (Fig. 1), condenser d^{12} , conductor c^8 , wiper c^{71} , conductor 48, switching-arm c^{84} , conductor 2, spring 16, contact-point 17, conductor 134, springs 6 and 7, conductor 133, receiver a^2 , conductor 132, secondary winding 131 of induction-coil a^4 , condenser a^5 , contact-point 36, spring 35, conductor 3, switching-arm c^{85} , conductor 49, wiper c^{72} , conductor c^4 , condenser d^{13} , "rotary-trunk-line-conductor" 5 (Fig. 1), "rotary-trunk-line-conductor" 5 (Fig. 2), switching-arm e^{82} , conductor 89, wiper e^{69} , conductor e^4 , condenser f^{109} , conductor 130, springs 129 and 128, switching arm f^{84} , contact-point f^{97} , wiper f^{71} , conductor f^4 , conductor 127, spring 126, contact-point 125, conductor 124, condenser b^1 , and back to secondary winding 170 of induction-coil b^5 . It will thus be seen that variations originating in the transmitter b^4 at sub-station #2220 will reach the calling subscriber's receiver a^2 at sub-station #6555, over a comparatively clear path, through condensers f^{108} and f^{109} at "connector" F, and condensers d^{12} and d^{13} at the repeater D. In like manner, variations produced in the transmitter a^2 at sub-station #6555 reach receiver b^3 at sub-station #2220 over the same path. After one subscriber has established connection with another, the instruments may be restored to their normal conditions, or released in different ways; a calling subscriber may hang up his receiver first; the called subscriber may hang up his receiver first; a called subscriber may begin to call before the calling subscriber has restored his receiver, or the called subscriber may not have answered at all. We may suppose, now, that the subscriber at substation #6555 restores the receiver a^2 to its hook a^0 before subscriber at sub-station #2220 restores his. It will be remembered that bridge-cut-off pole-changing-relay d^0 at the repeater D, as well as the "vertical" and "rotary" "line-relays" d and d^3 , are energized, their armatures being, therefore, attracted. Now, as soon as the hook a^0 is drawn down by the weight of the receiver a^2 , lug 173 on hook a^0 presses spring 174 against spring 175 and then both together against spring 176 momentarily, with the result that both "line-conductors" 2 and 3 are grounded at once, as follows: from ground 13 at sub-station A to springs 10 and 11, to conductor 15, to ground-spring 175, to springs 174 and 176, to conductors 169 and 134, to contact-points 36 and 17, to springs 35 and 16, to conductors 3 and 2, thereby short-circuiting the "vertical-line-relay" d at the repeater D, through ground as follows: from ground 13 at sub-station A to ground-spring 175 to spring 176, conductor 134, contact-point 17, spring 16, conductor 2, switching-arm c^{84} , conductor 48, wiper c^{71} , conductor c^3 , "vertical-line-relay" d , winding d^0 of differential-coil d^5 , springs 54 and 59 to ground 58; the "vertical-line-relay" d is thereby deenergized, while the "rotary-line-relay" d^3 retains its energized condition by reason of a circuit as follows: from ground 13 at sub-station A, through a circuit already traced, to conductor 3, switching-arm c^{85} , conductor 49, wiper c^{72} , "rotary-line-relay" d^3 , winding d^7 of differential-relay d^5 , conductor 56 to non-grounded terminal of battery H^1 , to ground h . Under these conditions, it will be seen that current passes only through winding d^7 of the differential-coil d^5 which, becoming active, attracts its armature d^8 , breaking contact between spring 66 and contact-point 67. It will be remembered that the energizing circuit in which were in-

cluded the windings of the differential-relay f^{102} and the "vertical" and "rotary" "line-relays" f^5 and f^7 at "connector" F, together with the bridge-cut-off pole-changing-relay 5 d^9 at repeater D, depended for its continuity upon the maintenance of contact between spring 66 and contact-point 67. As soon as "vertical-line-conductor" 2 from sub-station A is grounded by release-springs 176 and 175 10 coming in contact with each other, talking current ceases to flow through winding d^6 of differential-relay d^5 , and from ground 58 toward sub-station A. At that instant the differential-relay becomes energized, attracting 15 its armature, and thereby breaking contact between spring 66 and contact-point 67, thus restoring armature d^{10} of bridge-cut-off pole-changing-relay d^9 , and the armatures of "vertical" and "rotary" "line-relays" in "connector" F; but at the instant that spring 54 20 breaks away from spring 59, and closes with spring 55, "vertical-line-relay" d is again energized by current that now flows in a reverse direction—coming from sub-station 25 ground 13 over "line-conductor" 2, "vertical-line-relay" d , winding d^6 of differential-coil to springs 54 and 55 and to battery H^1 . The differential-relay thereby retains its energized condition and its armature d^8 . At the 30 instant that spring 60 at the repeater D closes with ground-spring 59, ground connection is restored to spring 57, and contact having been established between springs 63 and 64 the trunk-line-conductors 4 and 5 are 35 both grounded, momentarily, reenergizing "rotary-line-relay" f^7 at "connector" F through a circuit which has already been traced, and short-circuiting the "vertical-line-relay" f^5 through ground, as follows: 40 from ground 58 at repeater D to trunk-line-conductor 4 to "vertical-line-relay" f^5 through winding f^{103} of differential-relay f^{102} to springs 95 and 166 and to ground 167. As in the case of the repeater, no current will flow 45 through the "vertical-line-relay", nor through winding f^{103} of differential-relay f^{102} during this occurrence. As current is passing through the other winding the differential-relay will, therefore, be energized, attracting 50 its armature, opening the energizing circuit through magnet-cut-off-relay f^{98} and pole-changing-relay f^{100} , by breaking contact between spring 165 and contact-point 164. As soon as this occurs, pole-changing-relay f^{100} 55 releases its armature f^{101} , thereby causing spring 95 to break from spring 166 and to engage with spring 96. At that instant the "vertical-line-relay" is reenergized with current in reversed direction through a circuit 60 that has already been described, thereby closing contact between springs 178 and 179, the current in the differential-relay flowing in such directions that the armature is still retained. At the same time that the pole-changing-relay releases its armature, cut-off- 65

relay f^{98} releases its armature f^{96} , thereby restoring the ringer-relay, the "private-magnet" and the "release-magnet". Just as soon as the circuit of the "release-magnet" f^{20} is restored, the "release-magnet" becomes energized as follows: from ground 90 at "second-selector" E, to switching-arm e^{80} , through "back-release-relay" e^{99} , wiper e^{87} , spring 178 to spring 179, "release-magnet" f^{20} , conductor 208, springs 109 and 110, conductor 97, to non-grounded terminal of battery H^2 , to ground h^1 . Referring to Fig. 5, "release-magnet" f^{20} thus energized attracts its armature f^{21} against the pull of the retracting-spring f^{24} . In this way, the "double-dog" f^{29} is kicked inwardly, causing it to rotate about the pivots f^{81} and f^{82} , throwing lug f^{30} under slot f^{27} of "release-link" f^{25} , this link dropping over lug f^{30} . As the "double-dog" f^{29} is kicked in by "release-armature" f^{21} , it moves link f^{37} which, being pivoted on arm f^{79} , causes the "side-switch" to rotate about the pivots f^{77} and f^{78} , restoring the "side-switch" to its first or normal position. The shaft f^{39} , being thus 90 left to the action of coil-spring f^{64} , rotates back on the arm-rest f^{62} until the stop-arm f^{66} strikes the stop-pin f^{65} . At this juncture, the arm-rest f^{62} enters the slot f^{61} again, and the shaft by its own weight drops to its 95 original position, leaving the "connector-switch" completely restored or released. It will be remembered that while the "side-switch" of the "connector" was in its third position, guarding potential 100 was established at the "private-wiper", and thereby at the contact with which it was engaged, by placing it in connection with the grounded terminal of battery H^2 . It will also be remembered that by 105 way of the said "private-wiper" a circuit was established for energizing the bridge-cut-off-relay of the "first-selector" G (Fig. 2). It is evident, therefore, that as soon as the "side-switch" was returned to its first 110 position, due to the operation of the "release-magnet", guarding potential was removed from the "private-contact" with which the "private-wiper" was engaged, and also that the circuit through the cut-off-relay of the 115 "first-selector" G was broken, thereby restoring said "first-selector" G to its normal condition also. At the same time that the "release-magnet" of the "connector" F is energized, "back-release-relay" e^{98} of the 120 "second-selector" E is also energized, as was stated, thereby attracting its armature e^{97} and bringing springs 180 and 181 into contact with each other. In this way, "release-magnet" e^{20} is energized through the following circuit: from ground 182 to springs 180 and 181, to "release-magnet" e^{20} , conductors 82 and 72, to the non-grounded terminal of the battery H^2 , to ground h^1 . Referring to Fig. 4, "release-magnet" e^{20} , being thus mo- 125 130

mentarily energized, attracts its armature e^{21} against the pull of the retracting-spring e^{24} . In this way, "release-link" e^{25} is brought forward until the slot e^{26} falls over the lug e^{28} which, with the "release-armature" returns to its normal position and carries the "double-dog" e^{27} with it. This restores the "side-switch" to its first position, removing guarding potential from the 5 "private-wiper" and the point with which it is in contact. The shaft, being left to the action of the coil-spring e^{64} , rotates back upon the rest-arm e^{62} until the stop-arm e^{66} strikes the stop-post e^{65} . At this point, 10 the shaft clears rest-arm e^{62} at slot e^{61} and drops of its own weight to its normal position, the switch being thus restored. Returning to the repeater D: It was shown that as soon as the armature d^{10} of the 15 bridge-cut-off-relay d^0 was restored, both armatures of the "vertical" and "rotary" "line-relays" d and d^3 were attracted, while the release-springs 174, 175 and 176 at substation A were together. In this way, the 20 springs 184 and 185 were brought together, causing "back-release-relay" c^{101} of the "first-selector" C to be momentarily energized through the following circuit: from ground 50, switching-arm c^{83} , "back-release-relay" c^{101} , arm c^{70} , conductor c^1 , springs 185 and 184, dead resistance d^{11} , springs 54 and 55 to non-grounded terminal of battery H^1 , and to ground h . The "back-release-relay", being thus energized, attracts its armature 25 c^{102} , causing springs 54 and 186 to close in contact, thereby energizing "release-magnet" c^{20} as follows: from ground 187 to springs 186 and 54, to "release-magnet" c^{20} , conductors 188 and 24 to non-grounded terminal 30 of battery H^1 and to ground h . Referring to Fig. 3, the "release-magnet" c^{20} , being thus energized, attracts its armature c^{21} , causing "release-link" c^{25} to engage with the "double-dog" c^{27} , and releasing this "first-selector-switch", just as the "second-selector" was released, the mechanism being identical. As soon as the "side-switch" is restored to its first position, the guarding potential is removed from the "private-wiper", 40 leaving the line thereby open for further use—the armatures of the "vertical" and "rotary" relays of the repeater D being restored to their normal positions as soon as the hook at sub-station #6555 disengages 45 with the release-springs 174, 175 and 176. It is plain, therefore, that the restoring of the receiver to its hook at the calling substation brings the release-springs into momentary contact, thereby momentarily 50 grounding both "line-conductors" simultaneously, thereby operating the repeater so that it, in turn, causes the release of all switches involved in the established connection. After all the switches are restored, the 55 called subscriber restores his receiver to its

hook b , thereby momentarily grounding the "line-conductors" 127 and 117, thereby momentarily energizing the "vertical" and "rotary" "line-relays" g^2 and g^3 of his "first-selector" G, this first "selector" being similar to the "first-selector" in Fig. 3, the energizing of said "vertical" and "rotary" "line-relays" having the same effect as if "vertical" and "rotary" "line-relays" c^5 and c^7 were energized momentarily, closing springs 70 25, 26 and 40. The closing of springs 26 and 40 would energize the "private-magnet" c^{48} through a circuit that has already been traced. This "private-magnet" being energized would attract its armature c^{49} , thereby 75 causing spring 29 to break from spring 30 and to close contact with spring 195. The closing of spring 25 with spring 26 would energize the "release-magnet" c^{20} , as follows: from ground 27 to springs 26 and 25, 80 conductor 28, springs 29 and 195, conductors 196 and 197, "release-magnet" c^{20} , conductors 33, 34, 35 and 24 to the non-grounded terminal of battery H^1 and to ground h . This "release-magnet" would simply attract 85 its armature, nothing of importance resulting, as the switch is already restored. Had the "release-link", for any reason, been disengaged from the "double-dog" c^{27} , and had the shaft c^{59} been held in an "off-normal" 90 position, the armature c^{21} would thrust "release-link" c^{25} over lug c^{28} of the "double-dog" c^{27} , drawing it away from the shaft c^{59} as soon as the "release-magnet" deenergizes, leaving the shaft to the action of 95 gravity, which would restore it to its normal position. Now, assuming that the called subscriber #2220 should hang up his receiver before the calling subscriber, the result would be just as explained above; the 100 release-springs 190, 191 and 192 would be momentarily brought together, grounding the "line-conductors" 117 and 127. The grounding of the "line-conductor" 117 would result in short-circuiting the magnet-cut-off-relay f^{98} , through ground, as follows: 105 from ground 193 at sub-station #2220 through springs 161 and 162, conductor 194, release-springs 191 and 190, contact-point 119, spring 118, "line-conductor" 117, conductor f^8 , wiper f^{70} , contact f^{90} , spring f^{83} to springs 116 and 115, to conductor 114, magnet-cut-off-relay f^{98} , contact-point 164, spring 165 to switching-arm f^{82} and to ground 135 at "connector" F. It is evident 110 that this magnet-cut-off-relay would be deenergized, allowing its armature f^{99} to regain its normal position, and that springs 108, 109 and 110 would close contact, thereby 115 restoring the circuits of the operating magnets already referred to, among these the circuit of the "release-magnet" f^{20} . The "vertical" and "rotary" relays at the "connector" F, being held down by battery current in the trunking circuit to the repeater, 120 125 130

they maintain contact between springs 178 and 179, so that the instant that magnet-cut-off-relay armature f^{99} restores contact between springs 109 and 110, the "release-magnet" f^{20} is energized through the following circuit: from ground 90 at "second-selector" E to contact-point e^{93} to switching-arm e^{80} , "back-release-relay" e^{96} , "private-wiper" e^{67} , springs 178 and 179, "release-magnet" f^{20} , conductor 208, springs 109 and 110, conductor 97 to non-grounded terminal of battery H^2 , to ground h^1 . Being thus energized, the "release-magnet" releases the "connector-switch" in a manner already described, guarding potential being removed from the occupied "private-contact-point", leaving it open for further use, and also restoring the bridge-cut-off-relay at the "first-selector" G, leaving it in readiness to be used by subscriber #2220 when desired. "Back-release-relay" e^{98} at the "second-selector" E, having been energized with "release-magnet" f^{20} of the "connector" F, attracts its armature e^{97} , thereby closing springs 180 and 181, energizing the "second-selector-release-magnet" e^{20} through a circuit already described, releasing this switch also to its normal position and removing guarding potential from the "private-bank", throwing the trunk that had been in use open to any other subscriber that may wish to use it. When "connector" F was restored, its shaft, on returning to normal position, caused "line-wipers" f^{70} and f^{71} to break away from trunk-lines f^8 and f^4 . This being done, the circuit through pole-changing-relay f^{100} was broken, restoring the armature 101 to its normal position, and therefore spring 95 into contact with spring 96 only. In this way, the "vertical" and "rotary" "line-relays" f^6 and f^7 of "connector" F, and the bridge-cut-off-pole-changing-relay d^9 at repeater D, were in turn deenergized also. Referring to Fig. 1, as soon as the bridge-cut-off pole-changing-relay d^9 is deenergized, and its armature d^{10} returns to its normal position, spring 54 breaks from spring 59, thereby cutting off the talking current supply at sub-station #6555, deenergizing in turn the "vertical" and "rotary" "line-relays" d and d^3 , and allowing their armatures d^1 and d^4 to return to their normal positions. Now, as soon as the subscriber #6555 restores his receiver, as before, he momentarily grounds the "line-conductors" 2 and 3, simultaneously, in a manner already explained, thereby simultaneously energizing "vertical" and "rotary" "line-relays" d and d^3 which, attracting their armatures, cause springs 184 and 185 to come into contact, thereby energizing "back-release-relay" c^{101} , as follows: from ground 50 to switching-arm e^{83} , "back-release-relay" c^{101} , "private-wiper" e^{70} , conductor c^1 , springs 185 and 184, dead resistance d^{11} to springs 54 and 55, to the non-grounded terminal of battery H^1 , and to ground h . "Back-release-relay" c^{101} , being thus energized, will attract its armature c^{102} , closing springs 54 and 186, thereby energizing "release-magnet" c^{20} , restoring the "selector" C in a manner already described, as soon as the hood a^6 at sub-station #6555 disengages from the release-springs 174, 175 and 176; and at the same time allowing the "vertical" and "rotary" "line-relays" at the repeater D to resume their normal positions. It will be noticed that when the subscriber #6555 hangs up his receiver after subscriber #2220 has restored his—that when the "vertical" and "rotary" "line-relays" d and d^3 are simultaneously and momentarily attracted, not only do springs 184 and 185 come in contact, but springs 56, 57 and 59 also come in contact, thereby momentarily grounding the trunk-conductors 4 and 5 simultaneously. Referring to Fig. 2, this would cause "vertical" and "rotary" "line-relays" e^5 and e^7 , of the "second-selector" E, to be energized simultaneously through circuits already described. These relays would attract their armatures, causing springs 73, 74 and 84 to come into contact at once. Referring to Fig. 4, "rotary-line-relay" e^7 , by causing springs 84 and 74 to come together, would energize "private-magnet" e^{48} as before. This "private-magnet" being energized would attract its armature e^{49} which, through the means of the arm e^{54} , would cause spring 77 to separate from spring 78 and to come in contact with spring 198, which, when spring 78 engaged with spring 74, would energize the "release-magnet" e^{20} . This would attract "release-armature" e^{21} , but would have no utility or significance, as the switch is already released. Next, we will suppose that sub-station #2220 desires to call a subscriber whose number is 9, before sub-station #6555 hangs up his receiver. The subscriber will press button b^8 nine times with no results of consequence. He will now press button b^7 once. This opens the talking battery circuit at sub-station B, deenergizing thereby cut-off-relay f^{98} and pole-changing-relay f^{100} as soon as spring 126 separates from contact-point 125; but as soon as it engages with spring 199, "line-conductor" 127 is momentarily grounded, thereby reenergizing pole-changing-relay f^{100} through the following circuit: from ground 193 at sub-station B through springs 161 and 162 to conductor 194, springs 199 and 126, "line-conductor" 127, conductor f^4 , "line-wiper" f^{71} , contact-point f^{97} , switching-arm f^{84} , springs 128 and 129, conductor 130, pole-changing-relay f^{100} to non-grounded terminal of battery H^2 and to ground h^1 . Pole-changing-relay f^{100} being thus energized, while magnet-cut-off-relay f^{98} is deenergized, as before described, the "connector" F, as well as the "second-selector" E,

is released. Subscriber at sub-station B finding that no one answers, not having made connection will repeat his call. If sub-station #6555 now returns the receiver to its hook, the "first-selector" and the repeater (Fig. 1) will be released as before. Suppose that subscriber at sub-station #6555, after having established connection with sub-station #2220, receives no answer. As receiver ⁵ b^3 at sub-station B is not removed from its hook, no talking current will be furnished to the established circuits, so that neither the magnet-cut-off-relay f^{98} nor the pole-changing-relay f^{100} will be energized. Receiving ¹⁰ no response, the subscriber at station A will now hang up his receiver, thereby momentarily grounding his "line-conductors" 2 and 3, energizing the "vertical" and "rotary" "line-relays" d and d^3 at the repeater D. These, in a manner explained, will in turn ground trunk-conductors 4 and 5 momentarily, thereby energizing the "vertical" and "rotary" "line-relays" at "connector" F through circuits already traced. These "vertical" and "rotary" "line-relays", being thus energized, attract their armatures f^6 and f^8 , momentarily, bringing springs 178 and 179 into contact—resulting in the release of "connector" F and the "second-selector" E, ²⁰ in a manner already referred to. As a result of the "vertical" and "rotary" "line-relay-armatures" at the repeater D being simultaneously attracted, springs 184 and 185 engage in contact and also release the "first-selector" C and the repeater D as before. It will be noticed that the "first-selector" (Fig. 1) has three conductors 199, 200 and 201 leading from switching-arm c^{84} , spring c^{87} and switching-arm c^{85} , respectively. These ³⁰ conductors are known as "vertical-normal", "private-normal" and "rotary-normal", respectively, and lead to the banks of the "connector-switches" of the hundred to which said "first-selector" C belongs. Conductors, ³⁵ similar to these, are shown at f^3 , f^1 and f^4 (Fig. 2) at the "first-selector" G. Returning, now, to that stage in the calling of #2220 where subscriber at sub-station #6555 pressed the button a^9 twice, and button a^8 once, button a^9 twice again, and button a^8 once, button a^9 again twice, and button a^8 once, and button a^9 for the last time ten times, it only remaining for button a^9 to be pressed once to complete the desired connection, the switches being in the following positions: The "first-selector" C had cut in and established connection with the repeater D, and the repeater D, being connected with "second-selector" E, had caused it to be ⁵⁰ raised two steps and to establish connection with the "connector" F, which had been raised two steps and had also moved around ten points or steps, the "side-switch" being in the second position. Suppose, now, that ⁵⁵ the subscriber #2220 is busy—there are two conditions under which this may occur. First, when subscriber #2220 has been called by some other subscriber; and, second, when subscriber #2220 is calling. Assuming, first, that subscriber #2220 has been ⁶⁰ called, and referring to Fig. 5, it is evident that, if this is the case, there is a "connector-switch" "set-on" or connected with the line that leads to sub-station #2220, the wipers of which are "set-on" or connected to the ⁶⁵ tenth contact of the second row or level of their respective banks, and the "side-switch" of which is in the third position. Guarding potential will, therefore, be found on the tenth contact of the second row or level of ⁷⁰ the "private-bank" f , through a circuit similar to the following: grounded terminal h^1 of battery H^2 to ground 135 to "side-switch-wiper" f^{82} , conductors 202 and 136, "private-wiper" f^{99} to busy-bank-contact. Now, if the ⁷⁵ subscriber at sub-station #6555 presses button a^8 , the "rotary-line-relay" f^7 will be energized in a well-known manner, which will in turn cause the "private-relay" f^{48} to be energized through a circuit as before. The ⁸⁰ armature f^{49} of "private-relay" f^{48} will thus be attracted, and the arm f^{54} will separate springs 103 and 104 and close springs 203 and 204. In this way, the "release-magnet" f^{20} will be energized through the following ⁸⁵ circuit: from grounded terminal h^1 of battery H^2 through occupying-switch and circuit, not shown, to busy-bank-contact, "private-wiper" f^{66} , conductors 136 and 202, "side-switch-arm" f^{82} , contact-point f^{90} , conductor 205, springs 203 and 204, conductors ⁹⁰ 206 and 207, "release-magnet" f^{20} , conductor 208, springs 109 and 110, conductors 97 and 98 to the non-grounded terminal of battery H^2 , to ground h^1 . As soon as ⁹⁵ the "release-magnet" f^{20} is energized, the "release-armature" f^{21} will be operated, as usual, when "connector" F will be restored to its normal position. The subscriber at sub-station #6555 (Fig. 1), thinking that he ¹⁰⁰ has established the desired connection, will press the signal-button a^7 , with the result that the "vertical-line-relay" f^5 is energized, as before; but instead of the ringer-relay f^{106} being operated, the "vertical-magnet" ¹⁰⁵ f^9 is energized, owing to the fact that the "side-switch" is now in first position, and the "side-switch-wiper" f^{81} in contact with contact-point f^{85} . This circuit has already ¹¹⁰ been pointed out and explained. As soon, therefore, as the "vertical-armature" f^{12} is actuated, the shaft f^{59} is raised from its normal position, and the stop-arm f^{66} on said shaft being raised with it will allow springs f^{67} and f^{68} to come into contact with each ¹¹⁵ other. In this way, the receiver at sub-station #6555 (Fig. 1) is brought into a circuit where current of any suitable nature is provided, this current usually causing a buzzing sound that will notify the sub- ¹²⁰ 130

scriber that the party called is busy. This busy-current may be produced in any suitable way. In Fig. 2 it is supplied by having a circuit-interrupter K inserted in the 5 primary-circuit of a step-down induction-coil L. The primary-circuit of this induction-coil is as follows: from ground 209 to circuit-interrupter K, primary-winding L¹ of induction-coil L, conductor 210 to the 10 non-grounded terminal of battery H² to ground h¹. This interrupter-current induces a similar current in the secondary winding L² of induction-coil L, which reaches receiver a² at sub-station A by the 15 following circuit: from secondary winding L² of induction-coil L to conductor 211, contact-point f⁶⁸, spring f⁶⁷, contact-point f⁸⁸, switching-arm f⁸⁴, springs 128 and 129, conductor 130, condenser f¹⁰⁹, conductor e⁴, 20 wiper e⁶⁹, conductor 89, switching-arm e⁸², conductor 5, (Fig. 1), condenser d¹⁸, wiper e¹², conductor 49, switching-arm e⁸⁵, conductor 3, spring 35, contact-point 36, condenser a⁵, secondary winding 131 of induction-coil 25 a⁴, receiver a², conductor 133, springs 7 and 6, conductor 134, contact-point 17, spring 16, conductor 2, switching-arm e⁸⁴, conductor 48, wiper e⁷¹, conductor e³, condenser d¹², conductor 4, (Fig. 2), switching-arm e⁸¹, conductor 30 88, wiper e⁶⁸, conductor e³ "vertical-line-relay" f⁵, differential-relay f¹⁰², springs 95 and 96, conductors 97, 98 and 210 back to secondary winding L² of induction-coil L. The subscriber at sub-station #6555, 35 hearing a busy signal, will know that the number he has tried to call is busy, and will hang up his receiver, calling some other time. When receiver a² is restored to its hook, the release-springs 174, 175 and 176 40 will be brought into momentary contact in the usual way; the "vertical" and "rotary" "line-relays" at repeater D will be energized as usual, which in turn will energize the "vertical" and "rotary" "line-relays" at 45 "connector" F. The "release-magnet" of said "connector", together with the "back-release-relay" at the "second-selector" E, will be energized in the usual manner, releasing these two switches. The "back-release-relay" c¹⁰¹ of the "first-selector" C 50 will be energized by the repeater D, in the manner previously stated, which will in turn energize the "release-magnet" c²⁰, thus releasing the "first-selector" C as before, the 55 "vertical" and "rotary" "line-relays" resuming their normal positions as soon as the release-springs at sub-station B break contact. Suppose, however, that the subscriber #2220 is busy calling some other subscriber. 60 It will be remembered that when the subscriber at sub-station #6555 (Fig. 1) established connection with subscriber #2220, the "private-wiper" f⁶⁹ of "connector" F established connection also over "private- 65 normal-line" f¹ with the cut-off-relay g of

the "first-selector" G (Fig. 2) through the springs 138 and 137. In this way, the "first-selector" is connected by way of the "private-normal-line", similar to f¹, with the "private-contact" in the "connector-private-banks" corresponding to its number. It is plain, therefore, that if the subscriber #2220 has made a call, the stop-arm g⁸ (Fig. 2), similar to the stop-arm e⁶⁹ on the shaft c⁵⁹ (Fig. 3), will disengage from spring 137 75 (Fig. 2), similar to spring c⁶⁷ (Fig. 3), allowing it to break with spring 138, similar to spring c⁶⁹ (Fig. 3), and to come in contact with spring 213, similar to spring 68 (Fig. 3). The result is that guarding 80 potential is established at the "private-contact" corresponding to the #2220 in the "connector-banks" by connecting "private-normal" f¹ to a ground through springs 137 and 213. When the subscriber #6555 85 now tries to establish final connection, by pressing the button a⁸, the "rotary-line-relay" f⁷ of the "connector" F is actuated in the usual way, and in turn actuates the "private-relay" of said "connector", in a 90 manner already shown. As soon as the "private-armature" f⁴⁹ is engaged, springs 103 and 104 are separated, while springs 203 and 204 are drawn into contact, and the "connector-switch" will be released as before. The calling subscriber (Fig. 1), as soon as he presses the signaling-button, will receive the busy signal. He will then restore his receiver to its hook, thus releasing all the switches in a manner already stated, 100 leaving them in readiness for further calling. It is evident, therefore, that talking battery current is provided to the talking lines from two different points, i. e., from the "connector" and from the repeater. The 105 called subscriber, upon answering, closes the circuit which provides him with talking battery current from the "connector", through the pole-changing-relay f¹⁰⁰; the latter by shifting the normally non-grounded 110 terminal of the "vertical-line-relay" f⁵ to the grounded terminal of battery H², causes current to pass through both windings of the differential-relay and through the "vertical" and "rotary" "line-relays" f⁶ and f⁷ 115 and the bridge-cut-off pole-changing-relay d⁹ at repeater D. This bridge-cut-off pole-changing-relay in turn shifts the non-grounded terminal of the "vertical-line-relay" d to the grounded terminal of battery H¹, thereby furnishing talking battery current to the calling subscriber through both windings of the differential-relay d⁹ 120 and the "vertical" and "rotary" "line-relays" d and d⁸ as in the "connector" F. It 125 is clear, therefore, that while the talking current is furnished from two points, the second point—the repeater—is under the control of the first—the "connector". It is evident also that the differential-relay 130

and the "vertical" and "rotary" "line-relays" at the repeater have other functions in addition to that of operating their armatures to control other circuits. They are used as means to control the amount of talking current furnished to the calling subscriber, and at the same time are used as impedance to prevent cross-talk between two or more sets of lines that may be in use for talking purposes at the same time. It will also be noted that talking current is put on the called line at a point between the called 'phone and the condensers at the "connector"; and on the calling line between the calling 'phone and the condensers at the repeater; between the "connector" and repeater condensers, current flows during a conversation that energizes the repeater bridge-cut-off pole-changing-relay. There is also a dead resistance at this repeater, in series with the "back-release-relay" of the "first-selector", which is connected with it in the same way that the "release-magnet" at the "connector" is in series with the "back-release" of the "second-selector"; and this resistance depends on the voltage of the battery at the repeater station, in this case being about 60 ohms. It will be observed that the differential-relays in both the repeater and the "connector" are so wound that they will be magnetized if current flows through only one winding; or, under certain conditions, through both. For example: During a release, when the called subscriber has not answered, current will pass through both windings of the differential-relay and energizes it. But when a called subscriber answers, talking current passes through both windings of the relay, but it is not energized. It will be readily understood that the different coils employed in this system can be of any desirable resistance, according to the conditions to be met; but with respect to the repeater, good results are obtained by having "vertical" and "rotary" "line-relays", as well as the bridge-cut-off pole-changing-relay, of 500 ohms each.

It will be understood, of course, that the two exchanges can be of any suitable size or capacity, and that any suitable, known or approved trunking arrangement can be employed in and between two exchanges. For example, in Fig. 7, it is assumed that at central #2 the number of subscribers runs from 1000 to 5999, inclusive, while at central #1 the number of subscribers runs from 5999 to 10,000, inclusive. Consequently, and with this arrangement, in the former exchange—that is, at central #2—the first five levels l^1, l^2, l^3, l^4 and l^5 of the "first-selector-banks" F^2 are used solely for the purpose of establishing connection between subscribers of this particular exchange. The trunks or trunk-lines s^1, s^2, s^3 ,

s^4 , and s^5 —assuming the provision of only one trunk to a level—extending from these levels in their order, from first to fifth, lead to the "second-selectors" S^1, S^2, S^3, S^4 and S^5 in their order, from first to fifth, so as to 70 correspond to the "connectors" of the thousands with which they trunk. The first one, namely, S^1 , trunks only to "connectors" of the one thousand group; the second one, namely, S^2 , trunks only to "connectors" of 75 the second thousand group, and so on. In turn, the levels of each set of "second-selectors" lead, in their order, to the "connectors" C^1, C^2, C^3 , etc., in each thousand. For example, the first, second, third, etc., levels of 80 the trunks lead to the first, second, third, etc., hundred "connector" groups of each thousand, and so on. In the same exchange, namely, central #2, the last five levels l^6, l^7, l^8, l^9 and l^{10} of the "first-selector-banks" F^2 85 have trunks or trunk-lines t^6, t^7, t^8, t^9 and t^{10} leading to the "second-selectors" T^6, T^7, T^8, T^9 and T^{10} of the other exchange, namely, central #1, these trunks leading through repeaters r^6, r^7, r^8, r^9 , and r^{10} . For example, 90 the sixth level-trunk t^6 passes through its repeater r^6 to a "second-selector" T^6 , which latter is multiplied in with the other "selectors" of the six thousand group. Similarly, the trunk t^7 from the seventh level, 95 after passing through a repeater r^7 , reaches a "second-selector" T^7 , which latter is multiplied in with other "second-selectors" of the seven thousand group. In the first exchange, namely, central #1, the last five 100 levels B^6, B^7, B^8, B^9 and B^{10} of the "first-selector-bank" F^1 are used only for local calls. The sixth level B^6 connects with the group of "second-selectors" S^6 that have trunking connection to and with the six thousand group; and the seventh level B^7 bears a similar relation to the group S^7 of the seven thousand group, and so on. In this first exchange, the first five levels B^1, B^2, B^3, B^4 and B^5 have trunk-line connections, through 110 the medium of their repeaters r^1, r^2, r^3, r^4 and r^5 , with the "second-selectors" T^1, T^2, T^3, T^4 and T^5 of the second exchange, namely, central #2. It will also be seen that the first level B^1 , through the medium 115 of its repeater r^1 , connects with the "second-selector" T^1 that is multiplied in with the other "second-selectors" S^1 of the one thousand group, and so on. In this way, it is obvious that in each exchange one or more 120 levels of the "first-selector-banks" may be appropriated and employed solely for the purpose of giving service between subscribers of the same exchange, while one or more levels of the same "selector-banks" may be 125 appropriated and employed solely for the purpose of getting service between subscribers of different exchanges. In other words, a calling subscriber whose line extends to exchange or central #1 will establish con- 130

nection with a "second-selector" of this same exchange if the number of the called subscriber is above 6000, but will obtain connection with the "second-selector" of the 5 other exchange if the number of the called subscriber is below 6000. In a similar way, any subscriber of the second exchange will, in making a call, establish connection with a "second-selector" either in the same exchange 10 or of the other exchange, according to whether the number called is below or above 6000. Of course, as previously stated, the arrangement is preferably such that the numbers in one exchange extend from 1000 to 15 5999, while in the other exchange the numbers run from 5999 to 10,000, so that in this latter exchange the lowest number of any subscriber would be 6000. This arrangement, however, is only illustrative of one of 20 many ways of trunking between two automatic telephone exchanges. My improved arrangement for distributing or supplying talking and switching current from the central source, and my improved repeating apparatus, may be employed in connection with 25 any suitable, known or approved arrangement or grouping of the switches at the exchanges or central stations, and in connection with any suitable style of apparatus, or 30 any suitable method of trunking in and between the different exchanges.

With the foregoing arrangement, it will be seen that it is possible to give automatic telephone service between subscribers of different exchanges—that is, between subscribers of one exchange and those of another, notwithstanding the length and resistance of the trunk-lines, and regardless of other difficulties and conditions which ordinarily 35 make it impractical to attempt to give satisfactory trunk-line service between the two exchanges. The repeater, or repeating apparatus D, is composed, it will be seen, of five relay-coils and one dead-resistance-coil, 40 the arrangement being such that the line-relay-coils" d and d^3 are, together with the "differential-relay-coils" d^6 and d^7 , normally bridged across the trunk-line at one side of the condensers d^{12} and d^{13} , with the middle 45 point of the bridge normally connected to the negative or non-grounded pole of the battery H^1 . In this way, all current necessary for talking and switching purposes in the first exchange, namely, central #1, is 50 furnished from the said battery or other centralized source of supply H^1 ; but owing to the provision of condensers d^{12} and d^{13} , no current from this battery ever traverses the trunk-line-conductors 4 and 5 leading to the 55 other exchange. Consequently, the combined bridge-cut-off and pole-changing-relay d^9 is always energized by current from the battery H^2 , which latter is at the other exchange. It will also be seen that this relay d^9 is normally bridged across the trunk- 60

line composed of the conductors 4 and 5, and at a point in the "line-circuit" at the right of the condensers d^{12} and d^{13} . In this way, the relay d^9 is energized by a flow of current from the battery H^2 as soon as the 70 called subscriber takes down his receiver and thereby closes the "line-circuit". Evidently, however, the relay d^9 controls the supply of talking current from the battery H^1 to the calling subscriber's line, inasmuch as the energizing of this relay d^9 is necessarily accomplished by the switching in of the battery H^1 between the "line-relay-coils" d and d^3 , and by the consequent establishment of a 75 flow of battery current through a complete metallic talking circuit. With this arrangement, the relays d , d^3 and d^9 remain energized while the subscribers are talking; but while the relays d and d^3 are energized by current from the battery H^1 , it is obvious 80 that the current for energizing the relay d^9 comes from the other exchange—that is, from the battery H^2 . At the other exchange, the relays f^5 , f^7 , f^{98} and f^{100} remain 85 energized during the time the talking circuit is closed, and while the subscribers are talking. At such time, the relay-coils d , d^3 , d^6 and d^7 and the battery H^1 are connected up in series in a "line-circuit" including the calling subscriber's transmitter a^3 . Also, at 90 this time, the relays d^9 , f^5 , f^7 , the coils f^{103} , f^{104} , together with the battery H^2 , are all connected up in series in the trunk-line-circuit including the conductors 4 and 5, and also including the relay-contacts 66 and 67 95 controlled by the differential-relay of the repeater D. At the same time, the battery H^2 is connected up in series with the relays f^{98} and f^{100} , and in a "line-circuit" including the called subscriber's transmitter b^4 . 100 In this way, the talking circuit extending between the calling and called subscribers' stations, of a system of the size or capacity described, comprises three complete metallic battery circuits, which are all inductively 105 connected together by condensers, so as to make the sides of the said battery circuits practically continuous as far as voice currents are concerned, and two of which battery circuits include the same battery. In 110 other words, the battery H^2 is included in two complete metallic battery circuits which are inductively united together by the condensers f^{108} and f^{109} , and whereby the called subscriber's transmitter b^4 is connected in 115 parallel, and also the called subscriber's circuit-opening and closing contacts 159 and 160 are connected in parallel with the circuit-opening and closing contacts 66 and 67 of the repeater at the other exchange. 120 While the calling subscriber is performing the operation known as calling the number of the called subscriber, and which involves the production, in the calling subscriber's "line-circuit", of electrical impulses corre- 125 130

sponding to the different digits of the called subscriber's number, it is evident that the repeater D is capable, through the medium of its "line-relays" d and d^3 , of repeating these impulses in the trunk-line-circuit extending to the "second-selector" of the other exchange. In other words, every impulse or electrical condition set up in the calling subscriber's "line-circuit" is repeated in the 5 trunk-line-circuit extending to the other exchange, the said repeater D being adapted to perform operations which are practically the same as those performed by the subscriber's calling device. For example, if 10 the calling subscriber grounds one side of his line, the repeater immediately grounds the same side of the trunk-line; if the calling subscriber grounds the other side of his line, the repeater immediately grounds the 15 corresponding side of the trunk-line; and if the calling subscriber, in hanging up his receiver, momentarily grounds both sides of his line, the repeater immediately does the 20 same thing with respect to the two sides of the trunk-line running to the other exchange. Again, the repeater is useful in releasing the switches from the "connector" back to the "first-selector", in case the release is not effected by the calling 25 subscriber; for when the called subscriber is first to hang up his receiver, the relay d^9 of the repeater is, of course, deenergized, and this immediately establishes a circuit from the non-grounded pole of the battery 30 through the coil or dead resistance d^{11} , and through the "release-relay" c^{101} of the "first-selector" C, and thence to the grounded pole of the battery H¹. After calling the 35 number of the called subscriber, the calling subscriber rings the called subscriber in the usual way—that is, by pressing his ringing-button, and the single impulse thus transmitted over the "vertical-line-conductor" causes the "line-relay" d to produce a similar 40 impulse in the "vertical-line-conductor" of the trunk-line, and with the result that the ringer-relay in the conductor is energized in the usual manner. In releasing, as explained, the act of the calling subscriber 45 in hanging up his receiver produces a momentary grounding of both sides of his line, and this electrical effect is immediately repeated or duplicated by the repeater with respect to the two sides of the trunk-line extending to the other exchange. In this way, the calling subscriber can effect a release of 50 any and all switches which may have been called into use in the establishment of connection between the two subscribers' lines. 55 On the other hand, however, the called subscriber, as explained, can only release the switches of his own exchange, but in so doing he also deenergizes the relay d^9 of the repeater. When this is done, the repeater 60 is, of course, restored to its normal condition, both "line-relays" then being restored to their connection in parallel with the negative or non-grounded pole of the battery. Consequently, when the calling subscriber hangs up his receiver, he thereby immediately energizes the two "line-relays" d and d^3 , and thus closes the previously described "release-circuit" including the dead resistance d^{11} and the "release-relay" c^{101} , inasmuch as the energizing of these two "line-relays" closes the normally-open switch-point in the "release-circuit", consisting of two normally-separated springs 184 and 185. It will be remembered, in this connection, that at the time the calling subscriber hangs up his receiver, his "first-selector" C is still in the position necessary for maintaining connection with the repeater, and in such condition that the energizing-circuit of the "release-relay" c^{101} is closed at every point 70 except at the normally-open gap or break divided by the normally-separated springs 184 and 185. In other words, the called subscriber can release all switches in his own exchange; but with respect to the other 75 exchange, he can also restore the repeater to its normal condition, and can thereby place the "release-circuit" extending between the repeater and the "first-selector" C in readiness to be closed when the calling 80 subscriber hangs up his receiver. During conversation, the said "release-circuit" is, of course, closed between the contacts 184 and 185, but at this time it is also true that the "release-circuit" is open between springs 54 85 and 55. In a similar way, the energizing-circuit of the "release-relay" e^{98} of the "second-selector" is closed, during conversation, between the springs 178 and 179, but at this time the springs 109 and 110 are separated. 90 With this arrangement, no releasing occurs except when a release is desired or necessary, and in each case the releasing between switches—that is, between the automatic step-by-step switching machines—is accomplished over an additional or third trunk-line-conductor. 95

As previously stated, the resistance of any and all coils may be regulated or adjusted according to conditions and requirements of 100 different cases. With respect to the "connector," good results have been obtained by employing "line-relay-coils" of 500 ohms resistance each, and by adopting substantially the same resistance for each of the coils f^{98} 105 and f^{100} . The coils f^{103} and f^{104} may each be of substantially 100 ohms resistance, and the "release-magnet" f^{20} may be of 60 ohms resistance. In the repeater, the coils d^6 and d^7 110 may each be of substantially 100 ohms resistance, while the resistance-coil d^{11} may, like the "release-magnet" of the "connector" have a resistance of substantially 60 ohms. In the "selectors," the "release-relays" 115 may each have a resistance of substantially 120 125 ohms. In the "selectors," the "release-relays" may each have a resistance of substantially 130

$\frac{1}{2}$ ohm, these relays having what are commonly known as low-wound coils. In this connection, it will be seen that the function of the coil d^{11} is similar to one of the functions of the "release-magnet" f^{20} , inasmuch as each serves to insure a positive potential at all multiples of the "private-bank-contacts" which are connected temporarily with the "private-wipers" c^{70} and e^{67} . In other words, it will be seen that the "release-relays" of the "selectors" are employed as a medium of connection (while the "selectors" are in use) for connecting the positive or grounded pole of the battery with the "private-wipers" of the "selectors," and for thereby maintaining a positive potential at all multiple-contacts connected with the "private-bank-contacts" with which the said "private-wipers" are in engagement. In this way, the resistance between the non-grounded poles of the battery and the said "private-bank-contacts" is always greater than the resistance between such contacts and the positive pole of the battery, so that the desired results will be sure to take place whenever another "selector" attempts to cut in on the established connection, even should the other "selector" attempt, for instance, to make connection with the repeater D at the very instant that the circuit of the relay c^{101} is closed—that is, at the very instant the "selector" C is being released.

The "selectors," and also the "connectors," may be of any suitable, known or approved construction. The herein described "selectors" are of the type shown and described in Patent No. 815,321, granted March 13, 1906. The "connectors" herein shown and described are of the type disclosed in Patent No. 815,176, granted March 13, 1906. The subscribers' telephone sets, hook-switches, calling devices and other instruments may be of any suitable, known or approved construction. It is obvious that the different parts of the subscribers' apparatus can be easily adjusted for the purpose of insuring the performance of their different functions and operation in their proper order or sequence. For example, it is essential that in the subscribers' apparatus that the switch-hook be capable of pressing together the springs 174, 175 and 176 before the ground 13 is cut off by the separation of the springs 10 and 11, inasmuch as the restoration of the receiver to the switch-hook preferably brings about a release of the different switches, in the manner explained. With the foregoing arrangement, it will be seen that the repeater is similar to the "connector" in this respect,—namely, that in both cases the battery current is fed to the talking-circuit through the "line-relays," and also through the coils of the differential-relays. The "connectors," when put in use be-

tween subscribers of the same exchange, employ their "line-relays" f^5 and f^7 , and also the differential-relay-coils f^{103} and f^{104} , for feeding talking-current to the line of the calling subscriber. When a "connector" is put in use between subscribers of different exchanges, however, the "line-relay-coils" and the differential-relay-coils of the "connector" then simply feed battery current to the trunk-line for the purpose of keeping the relay d^9 of the repeater in an energized condition during conversation between the subscribers. The "line-relays" of the repeater, and the differential-relay-windings of the repeater, are adapted to feed current to the line of the calling subscriber only, and in this respect are similar to the corresponding windings or coils of the "connector," for a "connector" never employs its "line-relays" for feeding talking current in the direction of the called subscriber, nor does the repeater ever employ its "line-relays" for feeding talking-current over the trunk-line in the direction of the called subscriber. The repeater in the "connector," however, differs in this respect,—namely, that the relay arrangement of the "connector" is such that talking-current may pass through the "connector" and flow through circuits extending therefrom in both directions, and to both the calling and the called subscribers' lines when the "connector" is put in use between subscribers of the same exchange; while the repeater is only provided with means for feeding current in one direction,—to wit, in the direction of the calling subscriber's station. In other words, it is the battery or source of current at the called exchange which is always employed for maintaining battery current on the trunk-line between the two exchanges, and also on the line of the called subscriber; whereas the battery at the calling exchange or central station is only employed for supplying current to the calling subscriber's line, and to local circuits. In this way, current from the battery of the calling exchange never reaches any apparatus in the called exchange, while current from the battery of the called exchange is employed for energizing circuits extending between the two exchanges. It will be readily understood, in this connection, that all coils or windings which are necessarily in bridge across the talking-circuit during conversation are capable of developing sufficient self-induction to prevent any shunting or short-circuiting of the voice currents through the batteries, or through any of the bridges existing across the talking-circuit during conversation.

Obviously, with the combination and circuit arrangement involving the repeater, no third or releasing trunk-conductor is necessary between the first and second "selec-

tors"—that is to say, between the subscriber's individual-switch and the switch to which the trunk-line-conductors 4 and 5 extend.

What I claim as my invention is:

- 5 1. An automatic telephone system comprising a plurality of step-by-step switching machines having switching contacts, calling and called subscribers' lines temporarily maintained in connection with each other
- 10 through the medium of the switch-contacts of said step-by-step switching machines, a repeater bridged across the talking-circuit at a point between two of said switching machines, and means for supplying talking-current through the said repeater to the calling subscriber's line, and through one of said switching machines to the called subscriber's line, said repeater having a line relay responsive to the operating impulses and connected with the line for feeding talking current thereto while the subscribers are talking.
- 15 2. An automatic telephone system comprising a step-by-step switching machine having switching contacts, a calling subscriber's line temporarily connected with a called subscriber's line through the medium of the switch-contacts of said step-by-step switching machine, a repeater bridged across the talking-circuit at a point between the said switching machine and the calling subscriber's line, and means for supplying talking-current through the said repeater to the calling subscriber's line, and through the said switching machine to the called subscriber's line, said repeater having a line relay responsive to the operating impulses and connected with the line for feeding talking current thereto while the subscribers are talking.
- 20 3. An automatic telephone system comprising a plurality of step-by-step switching machines having switching contacts, calling and called subscribers' lines temporarily connected together through the medium of the switch-contacts of said step-by-step switching machines including a "first-selector", a "second-selector" and a "connector", together with a repeater bridged across the talking-circuit at a point between the first and second "selectors", and means for supplying talking-current through the repeater to the calling subscriber's line, and through the said "connector" to the called subscriber's line, said repeater having a line relay responsive to the operating impulses and connected with the line for feeding talking current thereto while the subscribers are talking.
- 25 4. An automatic telephone system comprising a complete metallic talking-circuit provided with a couple of condensers, said condensers being arranged in and at opposite sides of the circuit, a repeater having a pair of "line-relays" bridged across the talking-circuit at one side of said condensers, 65 and having another relay bridged across the talking-circuit at the other side of said condensers, together with a battery for energizing said "line-relays", said last-mentioned relay being provided with means for both opening and closing the bridge in which the "line-relays" are normally included, and for switching one of said "line-relays" into connection with either pole of the battery, whereby said "line-relays" are normally both connected with one pole of the battery, but whereby said battery is connected in series between the two "line-relays" when the said third relay is energized.
- 30 5. An automatic telephone system comprising a "line-circuit", a "release-relay", a pair of "line-relays" bridged across the "line-circuit", a magnet-cut-off and pole-changing relay also bridged across the circuit, and a battery for energizing said relays, the said cut-off and pole-changing relay being provided with means for disconnecting the "release-relay" from one pole of the battery, and for switching one of said "line-relays" from one pole to the other of 80 said battery, said battery having one pole normally connected with both of said "line-relays", and the energizing of said cut-off and pole-changing relay performing the two functions of disconnecting the "release-relay" from one pole of the battery and connecting the latter in series between the two "line-relays".
- 35 6. An automatic telephone system comprising a "line-circuit", automatic switching apparatus comprising a "line-relay", a "release-relay", a magnet-cut-off and pole-changing relay, together with a battery for energizing said relays, said cut-off and pole-changing relay being provided with means 100 for both opening and closing connection between the battery and said "release-relay", and for switching said "line-relay" from one pole of the battery to the other.
- 40 7. An automatic telephone system comprising automatic switching apparatus comprising a plurality of electro-magnets, a relay, and a battery and suitable connections for energizing said magnets and relay, said relay being provided with means 105 for both opening and closing connection between one of said electro-magnets and the battery, and for switching another of said electro-magnets from one pole of the battery to the other.
- 45 8. An automatic telephone system comprising a "line-circuit", a pair of "line-relays" bridged across said circuit, a battery having one pole normally connected with the bridge at a point between said "line-relays", a "release-relay", and a combined cut-off and pole-changing relay adapted to be controlled over said line circuit, said 110
- 50 120
- 55 115
- 60 125

cut-off and pole-changing relay being provided with means for controlling connection between the battery and the "release-relay", and for switching said battery in 5 series between the two "line-relays", together with another relay under the control of the calling subscriber and provided with normally closed switch-contacts connected in series with the winding of said 10 cut-off and pole-changing relay.

9. An automatic telephone system comprising a "line-circuit" having a condenser in each side thereof, a pair of "line-relays" bridged across the circuit at one side of said 15 condensers, a "release-relay" provided with a normally-open circuit controlled in part by said "line-relays", a combined cut-off and pole-changing relay, and a battery for energizing all of said relays, said cut-off and 20 pole-changing relay being provided with means for opening and closing connection between the battery and the "release-relay", and for switching one of said "line-relays" from one pole of the battery to the other, 25 said "line-relays" being normally both connected with the same pole of the battery, but said battery and "line-relays" being connected in series across the circuit when the said cut-off and pole-changing relay is 30 energized.

10. An automatic telephone system comprising a "line-circuit", a pair of "line-relays", a "release-relay", a cut-off and pole-changing relay, a differential-relay having 35 normally-closed switch-contacts connected in series with the winding of said cut-off and pole-changing relay, and a battery and suitable connections for energizing all of said relays, said cut-off and pole- 40 changing relay being provided with switch-contacts adapted for both opening and closing connection between the battery and the "release-relay" and for switching one of said "line-relays" from one pole of the 45 battery to the other, the circuit of the "release-relay" being normally open at the contacts of the "line-relays" and normally closed at the contacts of the cut-off and pole-changing relay, whereby the energizing of 50 said cut-off and pole-changing relay switches the battery in series between the two-line-relay-coils.

11. An automatic telephone system comprising a "release-relay", a pair of "line-relays", a cut-off and pole-changing relay, and a battery and suitable circuit connections for energizing all of said relays, the 55 normally-open circuit of the "release-relay" including normally-open contacts of the "line-relays" and normally-closed contacts of the said cut-off and pole-changing relay, and the circuits of a "line-relay" including both normally-open and normally-closed contacts of the said cut-off and pole- 60 changing relay.

12. An automatic telephone system comprising a repeater provided with "line-relays", a differential-relay, and a combined cut-off and pole-changing relay, a battery for energizing all of said relays, and a "release-relay", together with a normally-open circuit for said "release-relay", said circuit including normally-open contacts of the said "line-relays" and normally-closed contacts of the said cut-off and pole-changing 75 relay, and the said repeater being also provided with a resistance-coil forming part of said circuit and having a higher resistance than said "release-relay".

13. An automatic telephone system comprising a "connector", a repeater, a trunk-line connection between the repeater and the "connector", a battery for operating the repeater, and another battery for operating the "connector", said "connector" comprising 80 a pair of normally-bridged "line-relays", a magnet-cut-off-relay, a pole-changing-relay and a differential-relay, substantially as shown and described, and the said repeater comprising a pair of normally-bridged "line-relays", a combined cut-off and pole-changing relay, and a differential-relay, substantially as shown and described. 85

14. An automatic telephone system comprising a switch individual to a certain subscriber, a repeater, and means for supplying all necessary current, said switch being provided with a "release-relay" having a circuit extending to and controlled by the said repeater, said repeater having a line relay 95 responsive to the operating impulses and connected with the line for feeding talking current thereto while the subscribers are talking.

15. An automatic telephone system comprising a repeater and a plurality of electrically-propelled step-by-step switches, a calling subscriber's line temporarily connected with a called subscriber's line through the medium of said switches, two of said 100 switches being each provided with a "release-relay", the repeater having a coil of higher resistance than the said "release-relays", and another of said switches having a "release-magnet" which is also of higher 105 resistance than the "release-relay", together with a "release-circuit" including said "release-magnet" and one of said "release-relays", and another "release-circuit" including the said coil and the other "release-relay". 110

16. An automatic telephone system comprising a plurality of electrically-propelled step-by-step switches, a repeater, a calling subscriber's line temporarily connected with 115 a called subscriber's line through the medium of said apparatus, said repeater apparatus having a pair of "line-relays" and a pair of differential-windings and a battery bridged in series across the talking-circuit, 120 130

- 5 said repeater apparatus having also an additional relay bridged across the talking-circuit but inductively separated from the bridge containing said battery, and one of
 10 said switching machines having a pair of "line-relays" and a pair of differential-windings and a battery bridged in series across the talking-circuit and connected in series with said additional relay of the repeater apparatus, but said switching machine being also provided with a pair of relays connected in series with said last-mentioned battery and also bridged across the talking-circuit, the two bridges in which
 15 said last-mentioned battery is included being inductively separated from each other, whereby said first-mentioned battery supplies talking-current to the calling subscriber's line and whereby said last-mentioned
 20 battery supplies talking-current to the called subscriber's line.
17. An automatic telephone system comprising a temporarily established talking-circuit provided with two bridges each containing a separate battery and each also including a pair of "line-relays", said bridges being electrically connected with each other by inductive means in the talking-circuit, together with means whereby calling impulses transmitted through the relays of one bridge are repeated or reproduced in the windings of the relays included in the other bridge, and whereby talking and switching current is supplied independently to the two ends of the circuit by the said separate or independent batteries.
18. An automatic telephone system comprising a calling subscriber's line and a called subscriber's line temporarily connected together for conversational purposes, a pair of "connector-line-relay-coils" and a battery for supplying talking current bridged in series across the talking-circuit thus temporarily established between the two subscribers' stations, and another battery for supplying switching current and a pair of repeater-line-relay-coils bridged across the said talking-circuit, together with means for inductively connecting the two bridges with each other, whereby talking and switching current is supplied to the two subscribers' lines from two independent or separate sources, said repeater line relay coils being controlled by the calling subscriber to repeat impulses to the connector line relay coils during the establishment of the connection.
19. An automatic telephone system comprising an established talking-circuit, inductive connections in said talking-circuit, whereby the said talking-circuit is inductively-continuous for the purpose of transmitting voice-currents, but conductively non-continuous with respect to battery current, a pair of bridged "line-relays" at one side of said inductive connections, an elec-
 tro-magnet, an additional relay bridged across the circuit at the other side of said inductive connections, and means for supplying all necessary current, said additional relay being provided with a normally-closed 70 switch-point connected in series between the two "line-relays," and said electro-magnet being provided with a normally-open energizing circuit which also includes said normally closed switch-point.
- 75
20. An automatic telephone system comprising a talking-circuit, automatic switching apparatus comprising a "line-relay," an electro-magnet, an additional relay, together with a battery for supplying current, said "line-relay" having a terminal connected to be switched by said additional relay from one pole of the battery to the other, and said electro-magnet having a normally-open energizing circuit controlled at one point by 80 said additional relay.
- 85
21. An automatic telephone system comprising a plurality of step-by-step switches having switch contacts, a repeater, calling and called subscribers' lines temporarily maintained in connection with each other through the medium of said apparatus, said repeater bridged across the talking-circuit at a point between two of said switching machines, and means for supplying talking- 90 current through the said repeater to the calling subscriber's line, and through one of said switching machines to the called subscriber's line, means operated by battery current and under the control of any calling 95 subscriber for admitting alternating current onto any called subscriber's line and thereby producing an audible signal at the latter's station, said repeater having a line relay responsive to the operating impulses and 100 connected with a line for feeding talking current thereto while the subscribers are talking.
- 105
22. An automatic telephone system comprising a complete metallic talking-circuit 110 provided with a couple of condensers, said condensers being arranged in and at opposite sides of the circuit, a repeater having a pair of "line-relays" bridged across the talking-circuit at one side of said condensers, and having another relay bridged across the talking-circuit at the other side of said condensers, together with a battery for energizing said "line-relays," said last-mentioned relay being provided with means for both 115 opening and closing the bridge in which the "line-relays" are normally included, and for switching one of said "line-relays" into connection with either pole of the battery, said "line-relays" being normally both connected with one pole of the battery, but said battery being connected in series between the two "line-relays" when the said third relay is energized, means operated by battery current and under the control of any calling 120
- 125
- 130

subscriber for admitting alternating current onto any called subscriber's line and thereby producing an audible signal at the latter's station.

- 5 23. An automatic telephone system comprising a plurality of electrically-propelled step-by-step switches, a repeater, a calling subscriber's line temporarily connected with a called subscriber's line through the medium 10 of said apparatus, having a pair of "line-relays" and a pair of differential-windings and a battery bridged in series across the talking-circuit, said repeater apparatus having also an additional relay bridged across 15 the talking-circuit but inductively separated from the bridge containing said battery, and one of said switching machines having a pair of "line-relays" and a pair of differential-windings and a battery bridged in series 20 across the talking-circuit and connected in series with said additional relay of the repeater apparatus, but said switching machine being also provided with a pair of relays connected in series with said last- 25 mentioned battery and also bridged across the talking-circuit, the two bridges in which said last-mentioned battery is included being inductively separated from each other, whereby said first-mentioned battery supplies 30 talking-current to the calling subscriber's line and whereby said last-mentioned battery supplies talking-current to the called subscriber's line, means operated by battery current and under the control of 35 any calling subscriber for admitting alternating current onto any called subscriber's line and thereby producing an audible signal at the latter's station.

24. An automatic telephone system comprising a temporarily established talking-circuit, together with automatic switches for use in establishing the same, provided with two bridges each containing a separate battery and each also including a pair of "line-relays", said bridges being electrically connected with each other by inductive means in the talking-circuit, together with means whereby calling impulses transmitted through the relays of one bridge are repeated or reproduced in the windings of the relays included in the other bridge, and whereby talking and switching current is supplied independently to the two ends of the circuit by the said separate or independent batteries, means operated by battery current and under the control of any calling subscriber for admitting alternating current onto any called subscriber's line and thereby producing an audible signal at the latter's 60 station.

25. An automatic telephone system comprising an established talking-circuit, inductive connections in said talking-circuit, whereby the said talking-circuit is inductively-continuous for the purpose of trans-

mitting voice-currents, but conductively non-continuous with respect to battery current, a pair of bridged "line-relays" at one side of said inductive connections, an electro-magnet, an additional relay bridged across the circuit at the other side of said inductive connections, and means for supplying all necessary current, said additional relay being provided with a normally-closed switch-point connected in series between the two "line-relays", and said electro-magnet being provided with a normally-open energizing circuit which also includes said normally-closed switch-point, said electromagnet controlling said additional relay, means operated by battery current and under the control of any calling subscriber for admitting alternating current onto any called subscriber's line and thereby producing an audible signal at the latter's station.

26. An automatic telephone system comprising a talking-circuit, a "line-relay", an electro-magnet, an additional relay, together with a battery for supplying current, said "line-relay" having a terminal connected to be switched by said additional relay from one pole of the battery to the other, and said electro-magnet having a normally-open energizing circuit controlled at one point by said additional relay, said electromagnet controlling said additional relay, means operated by battery current and under the control of any calling subscriber for admitting alternating current onto any called subscriber's line and thereby producing an audible signal at the latter's station.

27. An automatic telephone system comprising a plurality of step-by-step switches having switch contacts, calling and called subscribers' lines temporarily maintained in connection with each other through the medium of said apparatus, and means for supplying talking-current through the said repeater to the calling subscriber's line, and through one of said switching machines to the called subscriber's line, and means whereby a subscriber may momentarily establish the live or charged ground-circuits necessary in calling the number of another subscriber, said repeater having a line relay responsive to the operating impulses and connected with a line for feeding talking current thereto while the subscribers are talking.

28. An automatic telephone system comprising a step-by-step switch having contacts, a calling subscriber's line temporarily connected with a called subscriber's line through the medium of said switch contacts, a repeater bridged across the talking-circuit at a point between the said switching machine and the calling subscriber's line, and means for supplying talking-current through the said repeater to the calling subscriber's line, and through the said switch-

- ing machine to the called subscriber's line, and means, whereby a subscriber may momentarily establish the live or charged ground-circuits necessary in calling the 5 number of another subscriber, said repeater having a line relay responsive to the operating impulses and connected with a line for feeding talking current thereto while the subscribers are talking.
- 10 29. An automatic telephone system comprising a plurality of step-by-step machines including first and second selectors and a connector having switch contacts, calling and called subscriber's lines temporarily connected together through the medium of said switch-contacts, a repeater bridged across the talking-circuit at a point between the first and second "selectors," and means for supplying talking-current 15 through the repeater to the calling subscriber's line, and through the said "connector" to the called subscriber's line, and means whereby a subscriber may momentarily establish the live or charged ground-circuits necessary in calling the 20 number of another subscriber, said repeater having a line relay responsive to the operating impulses and connected with a line for feeding talking current thereto while the 25 subscribers are talking.
- 30 30. An automatic telephone system comprising a "first-selector," a repeater, and means for supplying all necessary current, said "selector" having a "release-relay" provided with a circuit controlled by the repeater, and means whereby a subscriber may 35 momentarily establish the live or charged ground-circuits necessary in calling the number of another subscriber, said repeater having a line relay responsive to the operating impulses and connected with a line for feeding talking current thereto while the 40 subscribers are talking.
31. An automatic telephone system comprising a switch individual to a certain subscriber's line, a repeater, and means for supplying all necessary current, said switch being provided with a "release-relay" having a circuit extending to and controlled by 45 the said repeater, and means whereby a subscriber may momentarily establish the live or charged ground-circuits necessary in calling the number of another subscriber's line, said repeater having a line relay responsive to the operating impulses and connected with a line for feeding talking current thereto while the subscribers are talking.
- 50 32. An automatic telephone system comprising a calling subscriber's line, a called subscriber's line, a repeater and a plurality of electrically-propelled and step-by-step-actuated switching machines, said lines temporarily connected through the medium of said repeater and said switching machines; two of said switching machines 55 being each provided with a "release-relay", the repeater having a coil of higher resistance than the said "release-relays", and another of said switching machines having a "release-magnet" which is also of higher 60 resistance than the "release-relays", together with a "release-circuit" including said "release-magnet" and one of said "release-relays," and another "release-circuit" including the said coil and the other "release-relay", and means whereby a subscriber may momentarily establish the live or charged ground-circuits necessary in calling the 65 number of another subscriber.
- 70 33. An automatic telephone system comprising a plurality of electrically-propelled step-by-step switches, a repeater, a calling subscriber's line temporarily connected with a called subscriber's line through the medium of said apparatus, said 75 repeater apparatus having a pair of "line-relays" and a pair of differential-windings and a battery bridged in series across the talking-circuit, said repeater apparatus having also an additional relay bridged 80 across the talking-circuit but inductively separated from the bridge containing said battery, and one of said switching machines having a pair of "line-relays" and a pair of differential-windings and a battery 85 bridged in series across the talking-circuit and connected in series with said additional relay of the repeater apparatus, but said switching machine being also provided with a pair of relays connected in series 90 with said last-mentioned battery and also bridged across the talking-circuit, the two bridges in which said last-mentioned battery is included being inductively separated from each other, whereby said first-mentioned battery supplies talking-current to the calling subscriber's line and whereby said last-mentioned battery supplies talking-current to the called subscriber's line, and means whereby a subscriber may 95 momentarily establish the live or charged ground-circuits necessary in calling the 100 number of another subscriber.
34. An automatic telephone system comprising a temporarily established talking-circuit provided with two bridges each containing a separate battery and each also including a pair of "line-relays," said bridges being electrically connected with each other by inductive means in the talking-circuit, 105 together with means whereby calling impulses transmitted through the relays of one bridge are repeated or reproduced in the windings of the relays included in the other bridge, and whereby talking and 110 switching current is supplied independently to the two ends of the circuit by the said separate or independent batteries, and means whereby a subscriber may momentarily establish the live or charged ground- 115
- 120
- 125
- 130

circuits necessary in calling the number of another subscriber.

35. An automatic telephone system comprising calling and called subscribers' lines, a plurality of step-by-step switching machines, switch contacts therefor, said lines temporarily maintained in connection with each other through the medium of said switch contacts, a repeater bridged across the talking-circuit at a point between two of said switching machines, and means for supplying talking-current through the said repeater to the calling subscriber's line, and through one of said switching machines to the called subscriber's line, and means whereby a calling subscriber may momentarily establish the live or charged ground-circuits necessary in automatically effecting a disconnection between subscribers' stations after the conversation is terminated, said repeater having a line relay responsive to the operating impulses and connected with a line for feeding talking current thereto while the subscribers are talking.
- 25 36. An automatic telephone system comprising a step-by-step switch having contacts, a calling subscriber's line temporarily connected with a called subscriber's line through the medium of said switch-contacts, a repeater bridged across the talking-circuit at a point between the said switching machine and the calling subscriber's line, and means for supplying talking-current through the said repeater to the calling subscriber's line, and through the said switching machine to the called subscriber's line, and means whereby a calling subscriber may momentarily establish the live or charged ground-circuits necessary in automatically effecting a disconnection between subscribers' stations after the conversation is terminated, said repeater having a line relay responsive to the operating impulses and connected with a line for feeding talking current thereto while the subscribers are talking.
37. An automatic telephone system comprising a plurality of step-by-step switches including a first selector, a second selector and a connector having switch contacts, calling and called subscribers' lines temporarily connected together through the medium of said contacts, a repeater bridged across the talking-circuit at a point between the first and second "selectors," and means for supplying talking-current through the repeater to the calling subscriber's line, and through the said "connector" to the called subscriber's line, and means whereby a calling subscriber may momentarily establish the live or charged ground-circuits necessary in automatically effecting a disconnection between subscribers' stations after the conversation is terminated, said repeater having a line relay responsive to the operating im-

pulses and connected with a line for feeding talking current thereto while the subscribers are talking.

38. An automatic telephone system comprising a complete metallic talking-circuit provided with a couple of condensers, said condensers being arranged in and at opposite sides of the circuit, a repeater having a pair of "line-relays" bridged across the talking-circuit at one side of said condensers, and having another relay bridged across the talking-circuit at the other side of said condensers, together with a battery for energizing said "line-relays," said last-mentioned relay being provided with means for both opening and closing the bridge in which the "line-relays" are included, and for switching one of said "line-relays" into connection with either pole of the battery, whereby said "line-relays" are normally both connected with one pole of the battery, but whereby said battery is connected in series between the two "line-relays" when the said third relay is energized, and means whereby a calling subscriber may momentarily establish the live or charged ground-circuits necessary in automatically effecting a disconnection between subscribers' stations after the conversation is terminated.

39. An automatic telephone system comprising a "connector", a repeater, a trunk-line connection between the repeater and the "connector", a battery for operating the repeater, and another battery for operating the "connector", said "connector" comprising a pair of normally-bridged "line-relays", a magnet-cut-off-relay, a pole-changing-relay and a differential-relay, the said repeater comprising a pair of normally-bridged "line-relays", a combined cut-off and pole-changing relay, and a differential-relay, and means whereby a calling subscriber may momentarily establish the live or charged ground-circuits necessary in automatically effecting a disconnection between subscribers' stations after the conversation is terminated.

40. An automatic telephone system comprising a "first-selector", a repeater, means for supplying all necessary current, said "selector" having a "release-relay" provided with a circuit controlled by the repeater, and means whereby a calling subscriber may momentarily establish the live or charged ground-circuits necessary in automatically effecting a disconnection between subscribers' stations after the conversation is terminated, said repeater having a line relay responsive to the operating impulses and connected with a line for feeding talking current thereto while the subscribers are talking.

41. An automatic telephone system comprising a switch individual to a certain subscriber, a repeater, means for supplying all

- necessary current, said switch being provided with a "release-relay" having a circuit extending to and controlled by the said repeater, and means whereby a calling subscriber may momentarily establish the live or charged ground-circuits necessary in automatically effecting a disconnection between subscribers' stations after the conversation is terminated, said repeater having a line relay responsive to the operating impulses and connected with a line for feeding talking current thereto while the subscribers are talking.
42. An automatic telephone system comprising a repeater, a plurality of electrically-propelled step-by-step switches, a calling subscriber's line temporarily connected with a called subscriber's line through the medium of said apparatus, two of said switches being each provided with a "release-relay", the repeater having a coil of higher resistance than the said "release-relays", and another of said switches having a "release-magnet" which is also of higher resistance than the "release-relays", together with a "release-circuit" including said "release-magnet" and one of said "release-relays", another "release-circuit" including the said coil and the other "release-relay", and means whereby a calling subscriber may momentarily establish the live or charged ground-circuits necessary in automatically effecting a disconnection between subscribers' stations after the conversation is terminated.
43. An automatic telephone system comprising a suitable number of electrically-propelled and step-by-step-actuated switching machines, a suitable number of repeaters, and "release-circuits" for said switching machines, some of said "release-circuits" being controlled by certain of the switching machines, and other "release-circuits" being controlled by said repeaters, and means whereby a calling subscriber may momentarily establish the live or charged ground-circuits necessary in automatically effecting a disconnection between subscribers' stations after the conversation is terminated, said repeater having a line relay responsive to the operating impulses and connected with a line for feeding talking current thereto while the subscribers are talking.
44. An automatic telephone system comprising an established talking-circuit, inductive connections in said talking-circuit, whereby the said talking-circuit is inductively-continuous for the purpose of transmitting voice-currents, but conductively non-continuous with respect to battery current, a pair of bridged "line-relays" at one side of said inductive connections, an electro-magnet, an additional relay bridged across the circuit at the other side of said inductive connections, and means for supplying all necessary current, said additional relay being provided with a normally-closed switch-point connected in series between the two "line-relays", and said electromagnet being provided with a normally-open energizing circuit which also includes said normally-open switch-point, said electromagnet controlling said additional relay, and means whereby a calling subscriber may momentarily establish the live or charged ground-circuits necessary in automatically effecting a disconnection between subscribers' stations after the conversation is terminated.
45. An automatic telephone system comprising calling and called subscribers' lines, a plurality of step-by-step switching machines, switch contacts therefor, said lines temporarily maintained in connection with each other through the medium of said switch contacts, a repeater bridged across the talking-circuit at a point between two of said switching machines, and means for supplying talking-current through the said repeater to the calling subscriber's line, and through one of said switching machines to the called subscriber's line, and means whereby a called subscriber may momentarily establish the live or charged ground-circuits necessary in automatically effecting a disconnection between subscribers' lines after the conversation is terminated, said repeater having a line relay responsive to the operating impulses and connected with a line for feeding talking current thereto while the subscribers are talking.
46. An automatic telephone system comprising a calling subscriber's line, a called subscriber's line, a step-by-step switching machine, switch contacts therefor, said lines temporarily connected through the medium of said switch contacts, a repeater bridged across the talking-circuit at a point between the said switching machine and the calling subscriber's line, and means for supplying talking-current through the said repeater to the calling subscriber's line, and through the said switching machine to the called subscriber's line, and means whereby a called subscriber may momentarily establish the live or charged ground-circuits necessary in automatically effecting a disconnection between subscribers' lines after the conversation is terminated, said repeater having a line relay responsive to the operating impulses and connected with a line for feeding talking current thereto while the subscribers are talking.
47. An automatic telephone system comprising a plurality of step-by-step switches including a first selector, a second selector and a connector having switch contacts, calling and called subscribers' lines temporarily connected together through the me-

dium of said contacts, a repeater bridged across the talking-circuit at a point between the first and second "selectors", and means for supplying talking-current through the 5 repeater to the calling subscriber's line, and through the said "connector" to the called subscriber's line, and means whereby a called subscriber may momentarily establish the live or charged ground-circuits 10 necessary in automatically effecting a disconnection between subscribers' lines after the conversation is terminated, said repeater having a line relay responsive to the operating impulses and connected with a line for 15 feeding talking current thereto while the subscribers are talking.

48. An automatic telephone system comprising a complete metallic talking-circuit provided with a couple of condensers, said 20 condensers being arranged in and at opposite sides of the circuit, a repeater having a pair of "line-relays" bridged across the talking-circuit at one side of said condensers, and having another relay bridged across the 25 talking-circuit at the other side of said condensers, together with a battery for energizing said "line-relays," said last-mentioned relay being provided with means for both opening and closing the bridge in which the 30 "line-relays" are normally included, and for switching one of said "line-relays" into connection with either pole of the battery, said "line-relays" being normally both connected with one pole of the battery, but said battery being connected in series between the 35 two "line-relays" when the said third relay is energized, and means whereby a called subscriber may momentarily establish the live or charged ground-circuits necessary in 40 automatically effecting a disconnection between subscribers' lines after the conversation is terminated.

49. An automatic telephone system comprising a "line-circuit," a "release-relay," a 45 pair of "line-relays" bridged across the "line-circuit," a magnet-cut-off and pole-changing relay also bridged across the circuit, and a battery for energizing said relays, the said cut-off and pole-changing relay being provided with means for disconnecting the "release-relay" from one pole of the battery, and for switching one of said "line-relays" from one pole to the other of said battery, said battery having one pole normally connected with both of said "line-relays," the energizing of said cut-off and pole-changing relay performing the two 55 functions of disconnecting the "release-relay" from one pole of the battery and connecting the latter in series between the two "line-relays," and means whereby a called subscriber may momentarily establish the live or charged ground-circuits necessary in 60 automatically effecting a disconnection be-

tween subscribers' lines after the conversation is terminated.

50. An automatic telephone system comprising a "line-circuit," a "line-relay," a "release-relay," a magnet-cut-off and pole-changing relay, together with a battery for 70 energizing said relays, said cut-off and pole-changing relay being provided with means for both opening and closing connection between the battery and said "release-relay," and for switching said "line-relay" from one 75 pole of the battery to the other, and means whereby a called subscriber may momentarily establish the live or charged ground-circuits necessary in automatically effecting a disconnection between subscribers' lines 80 after the conversation is terminated.

51. An automatic telephone system comprising a calling subscriber's line, a called subscriber's line, a repeater and a plurality of electrically-propelled and step-by-step-actuated switching machines, said lines temporarily connected through the medium of said repeater and said switching machines, two of said switching machines being each provided with a "release-relay," the repeater 90 having a coil of higher resistance than the said "release-relays," and another of said switching machines having a "release-magnet" which is also of higher resistance than the "release-relays," together with a "release-circuit" including said "release-magnet" and one of said "release-relays," and another "release-circuit" including the said coil and the other "release-relay," and means whereby a called subscriber may momentarily establish the live or charged ground-circuits necessary in 95 automatically effecting a disconnection between subscribers' lines after the 100 conversation is terminated.

52. An automatic telephone system comprising a suitable number of electrically-propelled and step-by-step-actuated switching machines, a suitable number of repeaters, and "release-circuits" for said switching machines, some of said "release-circuits" being 110 controlled by certain of the switching machines, and other "release-circuits" being controlled by said repeaters, and means whereby a called subscriber may momentarily establish the live or charged ground-circuits necessary in 115 automatically effecting a disconnection between subscribers' lines after the conversation is terminated, said repeater having a line relay responsive to the operating impulses and connected with the 120 line for feeding talking current thereto while the subscribers are talking.

53. An automatic telephone system comprising a plurality of electrically-propelled step-by-step switches, a repeater, a calling 125 subscriber's line temporarily connected with a called subscriber's line through the medium of said apparatus, said repeater ap-

- paratus having a pair of "line-relays" and a pair of differential-windings and a battery bridged in series across the talking-circuit, said repeater apparatus having also 5 an additional relay bridged across the talking-circuit but inductively separated from the bridge containing said battery, and one of said switching machines having a pair of "line-relays" and a pair of differential- 10 windings and a battery bridged in series across the talking-circuit and connected in series with said additional relay of the repeater apparatus, but said switching machine being also provided with a pair of 15 relays connected in series with said last-mentioned battery and also bridged across the talking-circuit, the two bridges in which said last-mentioned battery is included being inductively separated from each other, 20 whereby said first-mentioned battery supplies talking-current to the calling subscriber's line and whereby said last-mentioned battery supplies talking-current to the called subscriber's line, and means 25 whereby a called subscriber may momentarily establish the live or charged ground-circuits necessary in automatically effecting a disconnection between subscribers' lines after the conversation is terminated. 30
54. An automatic telephone system comprising a temporarily established talking-circuit provided with two bridges each containing a separate battery and each also including a pair of "line-relays," said bridges 35 being electrically connected with each other by inductive means in the talking-circuit, together with means whereby calling impulses transmitted through the relays of one bridge are repeated or reproduced in 40 the windings of the relays included in the other bridge, and whereby talking and switching current is supplied independently to the two ends of the circuit by the said separate or independent batteries, and means 45 whereby a called subscriber may momentarily establish the live or charged ground-circuits necessary in automatically effecting a disconnection between subscribers' lines after the conversation is terminated. 50
55. An automatic telephone system comprising calling and called subscribers' lines, a plurality of step-by-step switching machines, switch contacts therefor, said lines 55 temporarily maintained in connection with each other through the medium of said switch contacts, a repeater bridged across the talking-circuit at a point between two of said switching machines, and means for supplying talking-current through the said 60 repeater to the calling subscriber's line, and through one of said switching machines to the called subscriber's line, automatic means for preventing any calling subscriber from establishing connection with a line which
- is busy or already charged with talking- 65 current from the centralized source of supply, said repeater having a line relay responsive to the operating impulses and connected with the line for feeding talking current thereto while the subscribers are talk- 70 ing.
56. An automatic telephone system comprising a calling subscriber's line, a called subscriber's line, a step-by-step switching machine, switch contacts therefor, said lines 75 temporarily connected through the medium of said switch contacts, a repeater bridged across the talking-circuit at a point between the said switching machine and the calling subscriber's line, and means for supplying 80 talking-current through the said repeater to the calling subscriber's line, and through the said switching machine to the called subscriber's line, automatic means for preventing any calling subscriber from establishing 85 connection with a line which is busy or already charged with talking-current from the centralized source of supply, said repeater having a line relay responsive to the operating impulses and connected with the 90 line for feeding talking current thereto while the subscribers are talking. 95
57. An automatic telephone system comprising a plurality of step-by-step switches including a first selector, a second selector, a connector, calling and called subscribers' lines temporarily connected together through the medium of the switch-contacts of said apparatus, a repeater bridged across the talking-circuit at a point between the first 100 and second "selectors", and means for supplying talking-current through the repeater to the calling subscriber's line, and through the said "connector" to the called subscriber's line, automatic means for preventing 105 any calling subscriber from establishing connection with a line which is busy or already charged with talking-current from the centralized source of supply, said repeater having a line relay responsive to the operating 110 impulses and connected with the line for feeding talking current thereto while the subscribers are talking. 115
58. An automatic telephone system comprising a complete metallic talking-circuit provided with a couple of condensers, said condensers being arranged in and at opposite sides of the circuit, a repeater having a pair of "line-relays" bridged across the talking-circuit at one side of said condensers, 120 and having another relay bridged across the talking-circuit at the other side of said condensers, together with a battery for energizing said "line-relays", said line relays each normally having a terminal connected with the same terminal of said battery, said last-mentioned relay being provided with means 125 for both opening and closing the bridge in

which the "line-relays" are normally included, and for switching one of said "line-relays" into connection with either pole of the battery, whereby said battery is connected in series between the two "line-relays" when the said third relay is energized, and automatic means for preventing any calling subscriber from establishing connection with a line which is busy or already charged with talking-current from the centralized source of supply.

59. An automatic telephone system comprising a "line-circuit", a pair of "line-relays" bridged across said circuit, a battery having one pole normally connected with the bridge at a point between said "line-relays", a "release-relay", and a combined cut-off and pole-changing relay adapted to be controlled by the called subscriber, said cut-off and pole-changing relay being provided with means for controlling connection between the battery and the "release-relay", and for switching said battery in series between the two "line-relays", together with another relay under the control of the calling subscriber and provided with normally-closed switch-contacts connected in series with the winding of said cut-off and pole-changing relay, and automatic means for preventing 25 any calling subscriber from establishing connection with a line which is busy or already charged with talking-current from the centralized source of supply.

60. An automatic telephone system comprising a "line-circuit" having a condenser in each side thereof, a pair of "line-relays" bridged across the circuit at one side of said condensers, said line relays each normally having a terminal connected with the same 35 terminal of said battery, a "release-relay" provided with a normally-open circuit controlled in part by said "line-relays", a combined cut-off and pole-changing relay, and a battery for energizing all of said relays, said 40 cut-off and pole-changing relay being provided with means for opening and closing connection between the battery and the "release-relay", and for switching one of said "line-relays" from one pole of the battery to 45 the other, whereby said battery and "line-relays" are connected in series across the circuit when the said cut-off and pole-changing relay is energized, and automatic means for preventing any calling subscriber from establishing connection with a line which is 50 busy or already charged with talking-current from the centralized source of supply.

61. An automatic telephone system comprising a "line-circuit", a pair of line-relays", a "release-relay", a cut-off and pole-changing relay, a differential-relay having normally-closed switch-contacts connected in series with the winding of said cut-off and pole-changing relay, and a battery and suitable connections for energizing all of said 65

relays, said cut-off and pole-changing relay being provided with switch-contacts adapted for both opening and closing connection between the battery and the "release-relay", and for switching one of said "line-relays" 70 from one pole of the battery to the other, the circuit of the "release-relay" being normally open at the contacts of the "line-relays" and normally closed at the contacts of the cut-off and pole-changing relay, and the 75 energizing of said cut-off and pole-changing relay switching the battery in series between the two "line-relay-coils", and automatic means for preventing any calling subscriber from establishing connection with a line 80 which is busy or already charged with talking-current from the centralized source of supply.

62. An automatic telephone system comprising a "release-relay", a pair of "line-relays", a cut-off and pole-changing relay, and a battery and suitable circuit connections for energizing all of said relays, the normally-open circuit of the "release-relay" including normally-open contacts of the "line-relays" and normally-closed contacts of the said cut-off and pole-changing relay, and the circuits of a "line-relay" including both normally-open and normally-closed contacts of the said cut-off and pole-changing 95 relay, and automatic means for preventing any calling subscriber from establishing connection with a line which is busy or already charged with talking-current from the centralized source of supply. 100

63. An automatic telephone system comprising a repeater provided with "line-relays", a differential-relay, and a combined cut-off and pole-changing relay, a battery for energizing all of said relays, and a "release-relay", together with a normally-open circuit for said "release-relay", said circuit including normally-open contacts of the said "line-relays" and normally-closed contacts of the said cut-off and pole-changing relay, 105 and the said repeater being also provided with a resistance-coil forming part of said circuit and having a higher resistance than said "release-relay", and automatic means for preventing any calling subscriber from establishing connection with a line which is 110 busy or already charged with talking-current from the centralized source of supply. 115

64. An automatic telephone system comprising a plurality of electrically-propelled and step-by-step-actuated switching machines, as many repeaters as there are switching machines, and a similar number of trunk-lines, each trunk-line terminating at one end in a switching machine and at the 120 other end in a repeater, automatic means for preventing any calling subscriber from establishing connection with a line which is 125 busy or already charged with talking-current from the centralized source of supply, 130

and a relay in said repeater responsive to operating impulses and connected with the talking circuit for charging it with talking current.

- 5 65. An automatic telephone system comprising a "connector", a repeater, a trunk-line connection between the repeater and the "connector", a battery for operating the repeater, and another battery for operating the "connector", said "connector" comprising a pair of normally-bridged "line-relays", a magnet-cut-off-relay, a pole-changing-relay and a differential relay, and the said repeater comprising a pair of normally-bridged "line-relays", a combined cut-off and pole-changing relay, and a differential-relay, automatic means for preventing any calling subscriber from establishing connection with a line which is busy or already charged with talking-current from the centralized source of supply.
- 10 66. An automatic telephone system comprising a "first-selector", a repeater, and means for supplying all necessary current, said "selector" having a "release-relay" provided with a circuit controlled by the repeater, automatic means for preventing any calling subscriber from establishing connection with a line which is busy or already charged with talking-current from the centralized source of supply, and a relay in said repeater responsive to operating impulses and connected with the talking circuit for charging it with talking current.
- 15 67. An automatic telephone system comprising a calling subscriber's line, a called subscriber's line, a repeater and a plurality of electrically-propelled and step-by-step-actuated switching machines, said lines temporarily connected through the medium of said repeater and said switching machines, two of said switching machines being each provided with a "release-relay", the repeater having a coil of higher resistance than the said "release-relays", and another of said switching machines having a "release-magnet" which is also of higher resistance than the "release-relays", together with a "release-circuit" including said "release-magnet" and one of said "release-relays", and another "release-circuit" including the said coil and the other "release-relay", automatic means for preventing any calling subscriber from establishing connection with a line which is busy or already charged with talking-current from the centralized source of supply.
- 20 68. An automatic telephone system comprising a suitable number of electrically-propelled and step-by-step-actuated switching machines, a suitable number of repeaters, and "release-circuits" for said switching machines, some of said "release-circuits" being controlled by certain of the switching machines, and other "release-circuits" being con-

trolled by said repeaters, automatic means for preventing any calling subscriber from establishing connection with a line which is busy or already charged with talking-current from the centralized source of supply, 70 each of said repeaters provided with a line relay responsive to operating impulses and connected with the line for charging said line with talking current.

69. An automatic telephone system comprising a plurality of electrically-propelled step-by-step switches, a calling subscriber's line having a calling device, said line temporarily connected with a called subscriber's line through the medium of said apparatus, the latter controlled and operated through the medium of said calling device at the calling subscriber's station, said switching machines including a pair of "line-relays" adapted to remain bridged 75 across the talking-circuit temporarily established for carrying on conversation between the two subscribers, and also including a pair of repeating-relays which remain bridged across the said talking-circuit 80 and through the medium of which the calling impulses transmitted by the calling subscriber are repeated in the windings of the said first-mentioned relays, automatic means for preventing any calling subscriber from 85 establishing connection with a line which is busy or already charged with talking-current from the centralized source of supply.

70. An automatic telephone system comprising a plurality of electrically-propelled step-by-step switches, a repeater, a calling subscriber's line temporarily connected with a called subscriber's line through the medium of said apparatus, said repeater apparatus having a pair of "line-relays" and a pair of differential-windings and a battery bridged in series across the talking-circuit, said repeater apparatus having also an additional relay bridged across the talking-circuit but inductively separated from the bridge containing said battery, and one of said switching machines having a pair of "line-relays" and a pair of differential-windings and a battery bridged in series 100 across the talking-circuit and connected in series with said additional relay of the repeater apparatus, but said switching machine being also provided with a pair of relays connected in series with said last-mentioned battery and also bridged across the talking-circuit, the two bridges in which said last-mentioned battery is included being inductively separated from each other, whereby said first-mentioned battery supplies talking-current to the calling subscriber's line and whereby said last-mentioned battery supplies talking-current to the called subscriber's line, automatic means for preventing any calling subscriber from 105 110 115 120 125 130

establishing connection with a line which is busy or already charged with talking-current from the centralized source of supply.

71. An automatic telephone system comprising a temporarily established talking-circuit, together with automatic switches for use in establishing the same, provided with two bridges each containing a separate battery and each also including a pair of "line-relays," said bridges being electrically connected with each other by inductive means in the talking-circuit, together with means whereby calling impulses transmitted through the relays of one bridge are repeated or reproduced in the windings of the relays included in the other bridge, and whereby talking and switching current is supplied independently to the two ends of the circuit by the said separate or independent batteries, automatic means for preventing any calling subscriber from establishing connection with a line which is busy or already charged with talking-current from the centralized source of supply.
72. An automatic telephone system comprising a temporarily established talking-circuit, a repeater apparatus, a suitable "connector", said repeater apparatus and "connector" both having relay-coils, together with a battery temporarily connected in series in a charged circuit including relays of both the repeater apparatus and the "connector", automatic means for preventing any calling subscriber from establishing connection with a line which is busy or already charged with talking-current from the centralized source of supply, one of the relays of said repeater responsive to operating impulses and connected with the line for charging the said line with talking current.

73. A telephone system comprising substation apparatus, a normally open ground connection at said substation, a central office exchange equipment, and a line circuit connecting the substation with the exchange, said line circuit comprising two line conductors, a repeater located in said circuit and provided with two line relays and a differential relay, the latter having two windings, a normally open line relay energizing circuit extending through the said substation ground connection and comprising one of the windings of the differential relay and one of said line conductors, another normally open line relay energizing circuit extending through the substation ground connection and comprising the other winding of the said differential relay and the other line conductor, whereby each time either of the said energizing circuits is closed the differential relay is energized also.

74. A telephone system comprising a selector provided with a release relay, an energizing circuit for said relay, and a re-

peater having a differential relay, the said differential relay responsive to impulses in establishing a connection and operative to control said circuit for releasing purposes.

75. A telephone system comprising a trunk release circuit, three relays conjointly controlling said circuit, the energizing of said circuit for release purposes being dependent upon the simultaneous energizing of said relays, line circuits also controlled by said relays, and means precluding the energization of one of said relays when the other two are necessarily energizing for the purpose of closing one of said line circuits.

76. In a telephone system, a line, a telephone for talking over said line, a switch, lines divided into groups, a relay for said switch, means for moving said switch, said means controlled by said relay for electing a group of said lines and controlled by said lines whereby a connection may be extended from the first line to any line in the elected group, and means for applying current for talking purposes to said telephone through the winding of said relay while the connection is maintained.

77. In a telephone system, a line, a telephone for talking over said line, a switch for said line, a relay for said switch, a group of lines having terminals in said switch, means for propelling said switch, circuits individual to said group of lines, said propelling means controlled by said individual circuits to stop the switch in association with an idle line of the group and for connecting the said first line with the idle line, said propelling means comprising an operating magnet and a step-by-step mechanism controlled by said magnet, an impulse sender for controlling said relay to operate said mechanism when stepped for each impulse, and means for supplying current for talking purposes to said telephone through the winding of said relay.

78. In a telephone system, a line, a telephone for talking over said line, a switch, a group of lines, a test circuit for each line of the group, a relay associated with said switch, means for moving the switch, said means controlled by said relay and controlled by said first circuits to continue the movement of the switch until the idle line in the group is found whereby a connection may be extended from the first line to said idle line, and means for supplying current for talking purposes to said telephone through the winding of said relay while a connection is maintained.

79. In a telephone system, a plurality of subscribers' lines, means including an automatic trunking switch for establishing a talking circuit between two of said lines, a battery bridged across said talking circuit, a relay for shifting one side of said circuit to the other pole of the battery, and a second

- relay in bridge of the talking circuit for controlling said first-mentioned relay. 65
80. In a telephone system, a plurality of subscribers' lines, means including an automatic trunking switch for establishing a talking circuit between two of said lines, a battery bridged across said talking circuit, a relay for shifting one side of said circuit to the other pole of the battery, and a double-wound relay in bridge of the talking circuit for controlling said first-mentioned relay. 70
81. A telephone exchange system comprising a repeater, a calling subscriber's line, a subscriber's telephone, a switch individual to said line and controllable from the subscriber's telephone, a release-circuit for conducting current to restore the said individual switch, provided with a normally-closed switch-point, the said switch adapted for connecting the subscriber's line with the repeater, and said repeater provided with a relay for controlling said switch-point in the release-circuit. 75
82. A telephone exchange system comprising a repeater, a calling subscriber's line, a subscriber's telephone, a switch individual to the subscriber's line, controllable from the telephone, a release-circuit for conducting current for releasing or restoring said individual switch, said switch adapted for connecting the subscriber's line with the repeater, said repeater provided with normally closed switch contacts and normally open switch contacts included in said circuit, and means for closing the said normally open switch contacts to send current over the release circuit to restore the individual switch. 80
83. In a telephone exchange system, subscribers' lines, means for establishing a connection between a calling and a called subscriber's line, said means including a repeater, a switch individual to said calling line and controllable from the subscriber's telephone, a connector having vertical and then rotary motion for seizing a called line, a release circuit for conducting current to restore the said individual switch, provided with a normally closed switch point, the said switch adapted for connecting the subscriber's line with the repeater, and said repeater provided with a relay for controlling said switch point in the release circuit. 85
84. In a telephone exchange system, the combination of an automatic switch mechanism, a pair of line relays allotted to said mechanism, local operating circuits for said mechanism directly controlled by said relays, an automatic switch also controlled by said relays, a calling telephone line, a called telephone line, and suitable instrumentalities for supplying talking current through the windings of said relays to the calling subscriber's line, and through the said automatic switch to the called subscriber's line. 90
85. In a telephone exchange system, the combination of a calling telephone line, a called telephone line, means including a selector switch and a connector switch for joining the two lines together, a pair of line relays for the selector, a pair of resistance windings for the connector, two common batteries or centralized sources of current supply, means for switching one battery in series between the two windings of the selector relays to supply current to the calling telephone line, and means for including the other battery in series between the resistance windings of the connector to supply talking current to the called telephone line. 95
86. In a telephone exchange system, the combination of a selector provided with a pair of line wipers and a pair of line conductors suitably connected therewith, a pole-changing relay bridged across the said line wipers, a pair of line relays bridged across the said line conductors, a battery having one pole normally connected between said line relays, a trunk line having a terminal temporarily engaged by said line wipers, means operated by the energizing of said pole-changing relay for switching the battery in series between the two line relays, and means for supplying current over the said trunk line and through the said wipers to energize said pole-changing relay. 100
87. In a telephone exchange system, the combination of a selector provided with a pair of line wipers and a pair of line conductors suitably connected therewith, a pole-changing relay bridged across the said line wipers, a pair of line relays bridged across the said line conductors, a battery having one pole normally connected between said line relays, a trunk line having a terminal temporarily engaged by said line wipers, means operated by the energizing of said pole-changing relay for switching the battery in series between the two line relays, means for supplying current over the said trunk line and through the said wipers to energize said pole-changing relay, and means by which a called subscriber controls the energizing of said pole changing relay. 105
88. An automatic selector switch comprising a pair of line wipers, a pole-changing relay bridged across the said line wipers, a pair of line conductors suitably connected with said line wipers, a pair of line relays bridged across said line conductors, a battery having one pole normally connected between said line relays, a differential relay having two windings each of which is connected in series with one of the line relays, an energizing circuit for the pole-changing relay controlled by said differential relay, means operated by the energizing of the pole-chang- 110
- 115
- 120
- 125

ing relay for switching the battery in series between the windings of the differential relay and the line relays, a trunk line temporarily seized by said line wipers, a source of energizing current, and means for connecting said source of current with the other end of said trunk line to supply current back through the said wipers and through the winding of the pole-changing relay to operatively energize the latter.

89. A common battery automatic telephone exchange system comprising a first selector provided with a release-relay, a repeater provided with a pair of line relays and a differential relay, together with a trunk release energizing circuit for said release relay, said circuit having two normally open switch points whereof one is controlled conjointly by said line relays, and the other is controlled by said differential relay, and means for supplying talking current to the calling line through said line relays.

90. A common battery automatic telephone exchange system comprising a trunk selecting switch mechanism provided with a release relay, a repeater provided with a pair of line relays and a differential relay, and a trunk release energizing circuit for said release relay, said energizing circuit having two normally open switch points whereof one is controlled conjointly by said line relays, and the other is controlled by said differential relay, and means for supplying talking current to the calling line through said line relays.

91. A common battery automatic telephone exchange system comprising a trunk-selecting switch mechanism, a repeater provided with four relay-coils through which talking current is supplied through the said trunk selecting switch mechanism to any calling subscriber's line, and a trunk release circuit connecting the trunk selecting switch mechanism with the repeater, said circuit having two normally open switch points whereof one is controlled by two of said relay coils, and the other is controlled by the other two relay coils.

92. A common battery automatic telephone exchange system comprising an electrically propelled and step-by-step actuated subscriber controlled switching machine, a subscriber controlled repeater, said repeater having a pair of line relays and a differential relay, and there being a trunk release circuit connecting the trunk selecting switch mechanism with the said repeater, said circuit having a plurality of serially related normally open switch points controlled by said line and differential relays.

93. A common battery automatic telephone exchange system comprising a trunk-

selecting switch mechanism, a trunk line, a repeater providing an inductive connection between the trunk-selecting switch mechanism and the trunk line, said repeater having a plurality of relays suitably connected between the trunk-selecting switch mechanism and the said inductive connection, together with a trunk release circuit extending between the trunk-selecting switch mechanism and the repeater, said circuit having a plurality of serially related normally open switch points controlled by said relays.

94. In a common battery automatic telephone exchange system, the combination of a connector provided with a pair of line relays and a differential relay, a trunk release circuit for said connector, said release circuit having normally open switch points controlled by said line and differential relays, subscribers' common battery transmitters adapted to receive talking current from the exchange or central station with which the same are connected, and subscribers' ringing keys associated with the said transmitters, together with means whereby the manual operation of any particular ringing key temporarily opens the talking circuit through its allotted transmitter and grounds one side of the line circuit to produce an audible signal at the station of any called subscriber.

95. In a common battery automatic telephone exchange system, the combination of a selector having release mechanism, a connector provided with a plurality of relays controllable by any calling subscriber using the connector, said connector having release mechanism, and there being a trunk release circuit extending between the selector and the connector for controlling the release thereof, said release circuit having a plurality of normally open switch points controlled by the said calling subscriber's relays of the connector, subscribers' common battery transmitters adapted to receive talking current from the exchange or central station with which the same are connected, and subscribers' ringing keys associated with the said transmitters, together with means whereby the manual operation of any particular ringing key temporarily opens the talking circuit through its allotted transmitter and grounds one side of the line circuit to produce an audible signal at the station of any called subscriber.

Signed by me at Chicago, Cook county, Illinois, this 17th day of May, 1905.

TALBOT G. MARTIN.
